ANTIPICK KEYLOCK MECHANISM

Carl Lurtz, Brooklyn, N. Y.

Application December 7, 1945, Serial No. 633,310

21 Claims. (Cl. 70—419)

1

This invention relates to key-lock-mechanisms, and is more particularly concerned with that type of locking mechanism which constitutes a separate key-operable unit whereby an interconnected securing device of one form or another may be operated; such interconnectable securing device usually takes the form of a bolt-mechanism or latch-mechanism adapted for holding a door or lid in shut position.

The invention in the present instance is embodied in a key-operable locking unit which comprises a plurality of tumblers or similar operating elements, arranged in a supporting frame in such a manner that locking-operation may be effected by means of a key having a notched operating edge whereby the tumblers may be shifted relative to one another to such position as to enable the lock to be operated.

Among the objects of the present invention may be noted the provision of means embodying elements adapted to render ineffectual the employment of a lock-picking device for urging all the tumblers of the lock, either collectively or individually, to the required operative position, to which position said tumblers may ordinarily be moved by means of the correct key.

In certain forms of the invention, as disclosed in the present application, the above mentioned object is accomplished in conjunction with a novel disposition of a plurality of tumblers, which, together with other essential operating parts of the lock-mechanism, are all carried on a rotatable supporting device inside a cylindrical housing; the latter embodying suitable operating elements maintained in position for co-action with the movable operating parts of the rotatable supporting device; said co-active operating elements of the housing comprise in the majority of the herein disclosed species of the present invention a stationary barricading device having deterrent-elements or barrier-elements disposed at a definite distance away from the normal position of the tumblers, so that it is necessary to first rotate the tumbler-support in either a clockwise or counter-clockwise direction over a limited angle to bring the tumblers in close proximity with the deterrent-elements of the stationary barricading device.

The rotatable tumbler-support is further adapted to carry a key-hole closing device, which, in association with certain elements of the lock-housing, enables the key-hole to be closed in such a manner during initial rotative movement of the tumbler-support that the remaining opening between the outside and the inside of the lock

2

precludes the possibility of reaching the tumblers by means of a stiff wire, or some similar rigid instrument whereby picking operation may be effected. Thus, with embodiment of the constructional features alluded to in this paragraph, there is no way of determining either before or after the key-hole is closed in what particular position any one of the several tumblers must be disposed in order to allow the gate of the respective tumblers to clear the barricading device.

The key employed in connection with the new lock-mechanism, embodying the present invention in one of its forms, possesses certain novel constructional features to enable the lock, with incorporation of a key-hole shutter, to be operated in the usual manner; that is to say, the notched part of the key is first inserted into the key-hole of the lock so as to cause all of the tumblers to be moved to the proper operating position, after which the freely rotatable operating parts inside the lock-housing may be turned by means of the projecting handle-part of the key in the desired angular direction as far as required for effecting operation in the interconnected bolt-mechanism.

The key-hole shutter of the present invention is so arranged that it passes through a slot of the key before the tumbler support is rotated far enough to bring any one of the tumblers in contact with, or vary close to, the stationary barricade whereby further movement of the tumbler-support in the same angular direction may be prevented if one or more of the tumblers are not disposed in the proper position relative to the barrier-elements of the barricading device.

The object of the present invention may further be achieved with the aid of means other than the above mentioned shutter device. Accordingly, the invention is exemplified in this application in several modified forms of construction, wherein the key-hole shutter is not incorporated; although it should be understood that any of said modifications may be constructed so as to include the key-hole shutter in the form of a supplementary device for attainment of maximum security in the lock.

In all those modifications of the invention which do not embody a key-hole shutter, the novel features reside principally in the means adapted for interlocking all of the tumblers while they are carried with the rotatable supporting device inside the housing over a limited initial angle in the direction of the barrier-elements; the latter being normally disposed at a definite distance away from the interceptable sections of

the tumblers. Hence, if in a construction of this type any of the several relatively movable tumblers is out of its proper position after having been interlocked, it would then be necessary to rotate the tumbler-support back to normal position in order to permit one or the other of the tumblers to be shifted to a different location on said support, thus, even in the absence of a key-hole shutter, it renders the procedure during attempted picking of the lock, exceedingly difficult and perplexing. However, the locking operation may be effected in a simple manner with the correct key, because when the key is inserted into the lock all of the tumblers are moved to the proper position, so that upon subsequent rotation of the key it enables the interlocked tumblers to clear the barrier-elements by virtue of the respective gates on the interceptable sections of the tumblers. The means for effecting said interlocking operation of the tumblers may embody detailed constructional elements of various form, as will be fully described hereinafter.

Other objects and advantages of the invention will in part be pointed out, and in part be apparent from the following detailed description and claims, when read in conjunction with the accompanying drawings, in which:

Fig. 1 is a front-view of the cylindrical housing, wherein the key-operable locking mechanism is accommodated, showing the form of the key-hole and the shutter therefore; part of the housing is shown broken away to reveal certain operating elements of the key-hole closing device.

Fig. 2 is another front-view of the cylindrical lock-housing, showing in dotted lines the tumbler supporting device rotated away from its normal position to a sufficient extent to effect closing of the key-hole by means of the shutter carried on the rotatable support.

Fig. 3 illustrates the form of the key, adapted for the operation of the lock-mechanism disclosed in the drawing-figures 1 and 2 through 14; the key is shown having a slot through which the shutter is permitted to pass when moved to the particular position indicated in Fig. 2.

Fig. 4 is a cross-sectional view of the lock-mechanism, taken on the section-line 60—60 of Fig. 1; revealing the arrangement of the pivoted tumblers and the disposition of the parts operatively associated therewith; the key is shown with its front-part inside the rotatable support for holding all of the tumblers in an operative position so that the lock may be operated.

Fig. 5 is a plan-view of the key-operable locking mechanism without its cylindrical housing, showing the pivotal connection of the tumblers, the stationary barricading ring, and the projecting end-section of the key-hole-shutter; a small portion of the substantially flat operating part of the key is shown to project outside the key-hole provided in the front-section of the tumbler-supporting device.

Fig. 6 is a rear-view of a latch-operating device, shown connected to an operating member which may be best seen in cross-section at the upper end of the device of Fig. 8.

Fig. 7 is a front-view of Fig. 5, having the key removed, and showing particularly the projecting end-portions of the tumblers as normally held at spaced relation with respect to the stationary barricading ring; the latter is shown partly broken away to permit a view of certain detailed constructional features of the mechanism.

Fig. 8 is a cross-sectional view of the locking mechanism, taken on the section line 61—61 of

Fig. 7; showing the arrangement of the various operating parts of the lock with the inclusion of the key-hole shutter; the key is shown endwise, partly inserted into the cylindrical lock-housing, which is indicated in dotted lines.

Fig. 9 is a rear-view of a limited number of operating parts, showing particularly the position of the pivoted tumblers in relation to the operating springs and the stationary barricading ring.

Fig. 10 is a rear-view of the open lock-housing, showing operating elements thereof adapted for interaction with elements of the tumbler-supporting device.

Fig. 11 is a cross-sectional view of the cylindrical lock-housing, taken on the section line 62—62 of Fig. 10.

Fig. 12 is a fragmentary view of the lock-housing, taken on the section line 63—63 of Fig. 11, and showing detailed constructional features on a certain edge-portion of the housing, adapted for co-action with an element of one of the tumblers for normally maintaining the tumbler-supporting device in a definite angular position so that the key-hole of the lock-housing is disposed in alignment with the key-hole of the rotatable tumbler-support while the latter is not being operated.

Fig. 13 is a side-view of a single pivoted tumbler, shown with embodiment of modified constructional features; the tumbler being shown in association with a fragment of the rotatable tumbler-support.

Fig. 14 illustrates certain operating parts of a latch-mechanism in connection with an operating element of the lock embodying the present invention.

Fig. 15 is a plan view of a modified form of the invention; the cylindrical housing being shown cut in half to reveal the assembled tumbler-mechanism, together with its key-hole shutter; the inserted key may be seen edgewise.

Fig. 16 is a front-view of the device of Fig. 15, taken approximately on the section-line 64—64 thereof, and showing the arrangement of the principal barricading elements of the lock in combination with the key-hole shutter, carried on the tumbler-support.

Fig. 17 is a side-view of a cylindrical casing which forms part of the rotatable tumbler-support.

Fig. 18 is a different side-view of the same casing which is shown in Fig. 17.

Fig. 19 is an illustration of the key suitable for the operation of the modified lock-mechanism, exemplified in the drawing figures 15 through 25.

Fig. 20 is a side-view of the rotatable tumbler-supporting device, shown without its cylindrical casing; the stationary barricading device, forming part of the lock-housing, is shown edgewise to indicate its position relative to the tumblers while the latter are disposed in a normal position.

Fig. 21 is a different side-view of the rotatable tumbler-supporting device, shown together with the stationary barricading member.

Fig. 22 is a front-view of the mechanism, which is seen sidewise in Fig. 20.

Fig. 23 is an enlarged cross-sectional view of the lock-construction shown in Fig. 22, and taken on the section-line 65—65 thereof.

Fig. 24 is a rear-view of the rotatable tumbler-support, showing detailed constructional features adapted for securing the latch-operating tong, the latter may be seen endwise in assembled position.

Fig. 25 is an end-view of the open tumbler-

casing, revealing certain detailed constructional features thereof.

Fig. 26 is a front view of a lock-construction, embodying the invention in modified form, without inclusion of a key-hole shutter.

Fig. 27 is a side-view of the completely assembled lock-mechanism inside the cylindrical housing, which is shown in cross-section.

Fig. 28 is a front-view of the lock, taken on the section line 66—66 of Fig. 27, and showing the arrangement of the tumblers on the rotatable support.

Fig. 29 shows the form of a key suitable for the operation of the modified lock-mechanism disclosed in Figures 26 through 38.

Fig. 30 is a cross-sectional view of the lock-mechanism, showing the arrangement of certain operating parts.

Fig. 31 is a front-view of the rotatable support with its tumblers, in association with the stationary barricading device, but without the cylindrical housing.

Fig. 32 is a front-view of the rotatable tumbler-support, stripped of all its removable elements.

Fig. 33 is a cup-shaped hub-member, which is provided with a key-hole, and is adapted for connection to the front-end of the tumbler-support, best seen in Fig. 32.

Fig. 34 is a plan-view of a latch-mechanism associated with operating elements of a padlock, showing in connection therewith a co-acting operating part of the novel key-operable lock-mechanism.

Fig. 35 is an enlarged front-view of the stationary barricade, together with the key-operable tumblers, shown disposed in their normal position relative to one another.

Fig. 36 is an enlarged side-view of one of the tumblers, shown in conjunction with a sectional view of the stationary barricade, taken on the section line 67—67 of Fig. 35; the tumbler is shown partly broken away to disclose certain operating elements on the rim of the barricade.

Fig. 37 is another enlarged view of the barricade and the tumbler, similar to that of Fig. 36, but showing the tumbler moved to that particular position in which its gate is enabled to clear the obstructing elements of the barricade.

Fig. 38 is an enlarged fragmentary view of the front-part of the lock-housing and the rotatable tumbler-support, showing the position of the key-hole of the tumbler-support in relation to the key-way in the lock-housing when said support is rotated away from its normal position over an arc of about 180°.

Fig. 39 is a front-view of another key-operable lock of modified construction, embodying the present invention.

Fig. 40 is a cross-sectional view of the modified lock-construction, taken on line 68—68 of Fig. 39.

Fig. 41 is a front-view of the mechanism illustrated in Fig. 40, taken on the section line 69—69 thereof, and showing the modified arrangement of the tumblers in conjunction with the modified barricading device.

Fig. 42 is a front-view of the rotatable tumbler-support, shown together with the stationary barricade.

Fig. 43 is a plan view of the key, adapted for the operation of the lock-mechanism disclosed in Figures 39 through 49.

Fig. 44 discloses a form of a key constructed so as to require an additional part to enable a lock to be operated thereby.

Fig. 45 discloses the additional key-part, adapted for connection to the key-part of Fig. 44; a section of the completed operating end of the key is shown in dotted lines.

Fig. 46 is an end-view of the operating part of the key shown in Fig. 45, and taken on the section line 70—70 thereof.

Fig. 47 is an enlarged cross-sectional view of the tumbler mechanism, including the stationary barricade, and taken approximately on the section line 71—71 of Fig. 48.

Fig. 48 is an enlarged front-view of the stationary barricade and the tumblers; the latter being shown in an operative position at a small angular distance away from the obstructing elements of the barricading device.

Fig. 49 is an enlarged plan-view of a padlock, shown with part of its casing broken away to reveal the interacting operating parts of the latch-device and the novel key-operable mechanism.

Fig. 50 is a front-view of still another modification of the invention.

Fig. 51 presents a view of the modified lock-mechanism in assembled position.

Fig. 52 is a sectional view of the lock, taken on the section line 73—73 of Fig. 51, and showing the arrangement of the tumblers on the rotatable support.

Fig. 53 is an illustration of the form of the key suitable for the operation of the modified lock-mechanism shown in Figures 50 through 59.

Fig. 54 discloses particular constructional features of the lever-locking device in association with the tumbler mechanism accommodated inside the cylindrical housing.

Fig. 70 is a rear-view of the tumbler-support, with the rear-plate thereof removed, to show the supporting elements for the tumblers and the springs of the lock-mechanism; and,

Fig. 71 is a cross-sectional view of the tumbler-mechanism, taken approximately on the section-line 74C—74C of Fig. 68.

DETAILS OF THE INVENTION

In the detailed description of the present invention, and in the appended claims, the term "tumbler-mechanism" is employed to generically designate a plurality of tumblers, together with the rotatable support and the adjunctive devices carried by the latter inside the lock-housing; while the term "barricading device" or "barriade," when used in the following description, is intended to designate the tumbler-obstructing device with embodiment of any or all of its constructional elements with aid of which the tumbler-mechanism may be prevented from being freely rotated, said barricading device may constitute a constructional feature of the lock-housing or a separate unit operatively associated therewith; and the term "key-hole shutter" or "shutter" is intended to generically designate the device whereby the key-hole of the lock may be closed or obstructed in a manner as specified in the following description.

Similar reference characters indicate corresponding parts throughout the several views of the drawing forming part of this application.

Tumbler lock mechanism including a key-hole shutter

The novel lock-mechanism, exemplified in the drawing-figures 1 through 14, embodies a key-hole-shutter 75, which in this particular species of construction forms one of the principal elements of the present invention, in conjunction with certain other constructional features of the mechanism. The shutter 75 is carried on the rotatable tumbler-support 76 (Fig. 5), which is accommodated in the cylindrical lock-housing 77. The rotatable support 76 is constructed so as to enable all the operable parts of the lock to be carried thereby. In the form shown, there are five tumblers pivotally held on said rotatable support by means of a shaft 78 (Figs. 5, 7 and 9); the tumblers being indicated respectively by the reference characters 79, 80, 81, 82 and 83.

The tumbler-spring 84, as best seen in Fig. 9, is made from a single piece of thin sheet metal, and is shown embodying five spaced-apart spring-blades, adapted for exerting spring-pressure separately on the tumblers close to their pivotal connection, so that all of the tumblers are normally urged forwardly in the direction of the key-hole 85, as far as permitted by the out-cut of the tumbler-support 76, wherein each tumbler is individually movable within a limited angle, as is apparent from an inspection of Figs. 4 and 8.

The lock-key 86 (see Fig. 3) is of unusual design; it embodies a substantially flat operating end 87, on the forward end of which are provided the graduated cuts 88 of varying depths, whereby the tumblers of the lock may be moved to different angular positions relative to one another, so as to bring the gate or outcut 89 (Fig. 4) of each tumbler into alignment with the barricading ring 90, thus affording the tumbler support 76 with all of its parts to be rotated by means of the key 86 after having been inserted into the lock to the full extent as shown in Fig. 4.

The barricading ring 90 is held in fixed position inside the housing 77; where the shoulder 91 is provided for holding the ring 90 seated with co-operation of the annular extension 92 (Fig. 4) of the connected rear-closure 93; the latter further embodies a flat bottom-section 94, adapted to retain the rotatable tumbler-support 76 inside its housing 77, so that the face 95, on the forward end of the tumbler-support, is maintained in very close proximity with the inside-face 96 (Figs. 4 and 10) on the front-wall of the housing 77, where the key-hole 97 is provided.

The key-hole 85 of the tumbler-support, when disposed in its normal position as shown in Fig. 1, is in exact alignment with the key-hole 97 of the lock-housing; but when the tumbler-support is rotated away from its normal position, as indicated in Fig. 2, then the major part of the key-hole 85 is hidden by the front-wall of the housing 77; the object of this particular arrangement in the lock-mechanism will be fully described hereinafter in connection with the key-hole closing device.

In order to prevent accidental displacement of the tumbler-support from its normal angular position, there is provided a detent element in the form of a depression 98 (Figs. 10, 11 and 12) on the shoulder-section 99 of the lock-housing 77; the said depression 98 is so located as to allow the front corner-portion 100 on the upper edge of the tumbler 81 (Fig. 8) to be spring-pressed into said depression, thus preventing the tumbler-support 76 from being rotated away from its normal position as long as the corner-portion 100 of the tumbler 81 remains in the depression 98. As shown in Figs. 10 and 12, there is provided a second depression 101 on one side of the depression 98, while on its other side there is a third depression 102; these two additional depressions are of such form that if the corner-portion 100 of the tumbler 81 is allowed to enter either one of said additional depressions it prevents the tumbler-support 76 from being rotated any further in a direction away from the depression 98; but upon movement of the tumbler-support toward its normal position it enables the tumbler 81 to slip out of the depression 101 or 102, as the case may be, by virtue of the sloping edge 103 or the other sloping edge 104 (see Fig. 12). The elements associated with said two additional

depressions come into operation only if picking of the lock is attempted, as will be elucidated in a later part of the specification in connection with the detailed description of the key-hole closing device.

As revealed in Figs. 7 and 9, the barricading ring 90 embodies a plurality of barrier elements, formed respectively on the left and the right end-section of said ring, at a definite distance away from the normal position of the interceptable parts of the tumblers, thus requiring the tumbler-support 76 to be first rotated over a small angle in order to bring into close proximity those sections of the tumblers in whose path the barrier-elements lie; the reference characters 105, 106 and 107 indicate respectively the three stepped barrier-elements on one side of the projecting ends of the tumblers, while the three other barrier-elements are indicated respectively by the reference characters 108, 109 and 110, see Fig. 9.

A small edge-portion of the barrier-element 105 and a similar portion of the barrier element 108 are adapted to respectively engage the projection 111 (Figs. 10 and 11) on the shoulder 91 of the lock-housing 77, so as to prevent angular displacement of the ring 90 from its proper position.

Now, one of the purposes for the stepped arrangement of the said barrier-elements is to enable more than one tumbler to be intercepted at one and the same time if operation of the lock is attempted by means other than the correct key; and if it is borne in mind that the key-hole of the lock is always obstructed whenever the tumblers are carried close to the barrier-elements, it will be apparent that the above mentioned arrangement of the tumblers contributes considerably to the security features of the lock, because if picking is attempted there is no means of determining, either before the key-hole is closed or afterwards, whether or not one or the other of the several tumblers has its gate disposed in proper position relative to the barricading ring 90.

Certain of the above related functional characteristics of the tumbler mechanism are closely interlinked with features of the key-hole closing device so as to enable maximum security in the lock to be attained. The shutter 75, forming the principal operating part of the key-hole closing device, is movably supported in the slot 113 (Fig. 8), which is made in the front-section of the tumbler-support 76, and is arranged so as to enable the said shutter to be normally held in the position shown in Fig. 1, where the projecting end of the shutter may be seen resting in the outcut 114; the latter being formed on the shoulder-section 99 of the lock-housing. If the tumbler-support 76 is rotated, to the left or right, away from its normal position, it forces the projecting end of the shutter 75 out of the outcut 114, thus urging the other end of the shutter into the key-hole 85, to obstruct it as shown in Fig. 2. During such initial angular movement of the tumbler-support 76, to the extent shown in Fig. 2, the tumblers are carried close to the barrier-elements of the ring 90; and in the event this partial movement of the tumbler-support should be effected without the use of a key, then it would be necessary first to push the tumbler 81 backwards, out of the depression 98. However, the same tumbler would afterwards be caught in one of the depressions next to the central depression 98, thus inhibiting further angular

movement of the tumbler-support in the same general direction. It would therefore be necessary to again move the tumbler 81 backwards to enable the tumblers to be carried into contact with the barrier-elements; but to carry out such operation is extremely difficult in practice due to the obstruction in the key-hole 85 and due to the hidden position of the small remaining openings of said key-hole behind the front-wall of the lock-housing. The tumbler-support 76 may, however, be easily returned, by means of a simple lever-device, from the aforementioned position (as shown in Fig. 2) to the normal position (as shown in Fig. 1), because the tumbler 81 is then allowed to ride back into the central depression 98 (Fig. 12) in the particular manner hereinabove described.

Whenever the tumbler-support 76 is rotated towards its normal position over the small angle indicated in Fig. 2, it affords the projecting outer end of the said shutter 75 to re-enter the outcut 114 by force of the cylindrical spring 115, thus effecting withdrawal of the other end-section of the shutter 75 from the key-hole 85. The spring 115 (see Figs. 5 and 8) is accommodated in a hole disposed rearwardly of the shutter-slot 113 in the tumbler-support, so as to enable the projecting member 116 of the shutter 75 to engage the outer end of the spring 115; the latter being shown resting with its other end on a small movable ball 117 (Fig. 8), which in turn is supported by a flange on the end of the hole so as to allow a portion of the ball 117 to project into the key-hole 85 of the tumbler-support 76. Thus the spring 115 is capable of holding the ball 117 yieldably in position, while pressing with its outer end against the shutter-member 116 to permit the aforementioned movement in the shutter 75 to be effected.

When the key 86 is inserted into the key-hole of the lock, it first pushes the ball 117 out of its way, and afterwards allows the said ball to enter with its projecting portion into the triangular outcut 118 (Fig. 3) of the key, thus enabling the latter to be held with sufficient pressure-contact in the key-hole to prevent the five key-engaging tumblers from pushing the key outwardly, by force of the tumbler-spring 84, if the operator should release his grip on the key before turning it in the lock. As shown in Fig. 3, the operating part 87 of the key 86 embodies a slot 119, made of suitable dimensions and arranged so as to allow the end-section of the shutter 75 to pass through said slot of the key during operation of the lock. The key 86 is further shown provided with a shoulder 120, formed on the neck or stem 121, for the purpose of limiting inward movement of the key when said shoulder 120 is brought in abutment with a portion on the front-section of the tumbler-support 76. As shown in the drawing, there are two additional shoulders 122 and 123 formed on the rear-end of the operating part 87 of the key 86; these additional shoulders are adapted to prevent the key from being pulled out of the key-hole after the tumbler-support is rotated away from its normal position, because the shoulders 122 and 123 are then located behind the front-wall of the lock-housing 77.

In Fig. 4 the key 86 is shown inserted as far as it goes, at which time the operating part 87 is entirely inside the key-hole 85 so that the said shoulders 122 and 123 are flush with the front-face of the tumbler-support 76; but in Fig. 5 the key is shown not inserted to the full limit as per-

11

mitted by the shoulder 120, thus exposing to view part of the key-section which embodies the shoulders 122 and 123.

As is self-evident, the lock can be operated only if the key 86 is inserted into the mechanism to the extent shown in Fig. 4, because all of the tumblers of the lock are then properly aligned relative to the barricading ring 90, and the operating part 87 of the key is then in proper position to permit a section of the shutter 75 to pass through the key-slot 119, while the shoulders 122 and 123 are held clear of the key-hole 97 of the lock-housing 77. During the initial angular movement of the key, together with the tumbler-mechanism, it causes the shutter 75 to be moved to the dotted-line position shown in Fig. 2 (if rotation is effected in a counter-clockwise direction), so that that end-section of the shutter which is adapted to obstruct the key-hole, is then located in the key-slot 119. It will therefore be apparent that the same initial rotative movement in the tumbler-support 76 cannot be effected by means of a makeshift instrument if inserted into the key-hole 85 far enough to obstruct the free movement of the shutter 75. However, the tumbler-support 76 may be rotated away from its normal position over a small angle even without the correct key, if the tumbler 81 is first pushed back so as to disengage it from the depression 98 (Fig. 12), and if the temporary lever-contrivance is manipulated so as not to get in the way of the shutter 75 while the latter is urged into the key-hole 85. Assuming now that the tumbler-support 76 is rotated to the angular position shown in Fig. 2, without employment of the correct key, in such case the key-hole of the lock is so effectively obstructed that the hidden tumblers cannot be moved to the proper position relative to the barricading ring 90 by means of some makeshift instrument manipulated from the outside of the lock.

It should be noted that the key-hole 97 of the lock-housing is provided with two ward-members 124 (Figs. 1 and 10), spaced apart from each other to approximately the width of the shutter 75. The key-hole 85 of the tumbler-support 76 also has two spaced-apart wards 125 similarly disposed; thus the key-hole 85 is very nearly identical in form with the key-hole 97; the only difference being that the key-hole 97 of the lock-housing embodies the circular hole 126, wherein in the stem 121 of the key 86 is adapted to rotate. Whereas the key-hole 85 of the tumbler-support 76 (see Figs. 7 and 8) embodies merely a centrally disposed conical depression 112 (see Fig. 8) for receiving a similarly formed portion formed on the forward end of the key-stem 121.

Bearing in mind the aforementioned features of the two separate key-holes in the lock, it will be evident from an inspection of Fig. 2 that when the shutter 75 is in position to obstruct the key-hole 85 of the tumbler-support 76, the remaining openings between the outside and the inside of the lock assume the form of two tortuous channels; one of said channels leading around one edge of the shutter 75, and the other channel leading around the other edge of said shutter in the key-hole 85.

Any wire or similar instrument that is desired to be inserted into the lock, while the tumbler-support is in the position shown in Fig. 2, must of necessity be easily bendable, and even such wire could be pushed through the tortuous channel only with great difficulty, because before reaching the small opening on either one or

12

the other side of the shutter 75, there is a bend formed in the channel by the ward 125 of the key-hole 85; the next bend is formed around the edge of the shutter 75, and in back of the latter there is still another bend formed by the ward 125. Thus, even if one should succeed to force the end of a bendable wire in back of the shutter 75, the wire could not possibly serve for moving the tumblers to the proper position relative to the barricading ring 90; mainly because the inserted part of the wire would be held too tight inside the tortuous channel. Furthermore, one wire alone would be entirely inadequate for effecting movement in more than one tumbler inside the lock, and any attempt of forcing one or two additional wires through the same channel in which there already is another wire, would prove entirely futile for the purpose of disposing the several tumblers in such position as to permit operation of the lock.

If desired, the outer shell of the lock-housing may be made of hardenable steel, in which case it may be found preferable for reasons of economy to form the shoulder 91 together with the shoulder-section 99 as a separate unit to be joined to the said steel shell so as to form a housing as illustrated in the drawing. If the lock-housing is made entirely of brass, then the quality of the housing may be improved by securing a hard steel plate 127 (see Fig. 11) to the front-wall of the cylindrical shell 77 on its inside.

The handle-part 128 of the key 86 is shown having one side with a smooth surface, as indicated in Fig. 5, and the other side with a rough surface (Figs. 3 and 4) made by the imprints 129, thus enabling the user of the key, when gripping its handle-part 128, to determine by feel whether the key is properly held in the hand in relation to the key-hole of the lock which is desired to be operated.

The tumbler-mechanism of the lock is constructed so as to enable all the parts thereof to be assembled with minimum effort and time. For example, the five tumblers (as seen in Fig. 9) may be gripped by the hand so that all of them may be inserted together into the outcut of the tumbler-support 76; the latter embodying the supporting element 130 (Figs. 5 and 13) adapted for receiving the round pivotal end-sections of the tumblers; the loosely fitting shaft 78 may then be pushed in through the respective pivot-holes of the tumblers, allowing each projecting end of the shaft 78 to rest in a semi-circular depression 131 of the tumbler-support 76 (Figs. 5 and 7), thus affording the tumblers to be held pivotally connected with co-operation of said supporting element 130. After the aforementioned assembly operations, the tumbler-spring 84 is attached to the tumbler-support 76, as illustrated in Figs. 4 and 8. The spring 84 is shown provided with an anchorage element 132 (Figs. 8 and 9) which is adapted to enter a depression (see Fig. 8) on the rear-wall of the tumbler-support 76 for retaining the spring 84 in assembled position; in addition to the anchorage element 132, there are other suitable elements embodied with the mechanism for holding the tumbler-spring 84 properly attached; among these elements may be mentioned the provision of suitable grooves on the tumbler-support 76 into which the left- and right-hand side edges of the spring 84 are adapted to respectively project.

A slightly modified form of tumbler construction is exemplified in Fig. 13, where the tumbler

is indicated by the reference character 81A, and may be regarded to take the place of the tumbler 81 which may best be seen in Fig. 8. The modifications in the tumbler 81A apply principally to the form of operating springs that may be incorporated with the pivoted tumblers if suitably made. For instance, an open cylindrical spring 84A, supported in a hole of the tumbler 81A as shown in the drawing, may be employed for effecting the necessary spring-action in the tumbler; the projecting end of the cylindrical spring 84A being adapted to press against the rear-wall of the tumbler-support 76. Instead of the said cylindrical spring 84A, a straight wire-spring or blade-spring 84B may be used for urging the tumbler forwardly in the direction of the key-hole in the lock, if the said blade-spring is properly secured to the tumbler, as exemplified in Fig. 13. The gate 89 is shown in dotted lines on the tumbler 81A; said gate may be cut anywhere on the peripheral edge of the tumbler so as to be movable into alinement with the barricading ring 90 by means of the key that is fitted for the operation of the lock.

The lock-mechanism, embodying the present invention, is of a construction that may be employed as an operating unit in combination with various types of latch-mechanisms, provided a suitable latch-operating device is incorporated with the rotatable tumbler-support; whether that be of the form shown in Fig. 5, or any other form disclosed in the several views of the drawings in this application. In connection with the particular lock-construction illustrated in Figs. 4 and 5, the tumbler-support 76 is shown embodying at its rear-end a short stem 133, which is adapted to carry the latch-tongue 134; the latter includes certain novel constructional features co-active with features on the stem 133 for holding the two last-mentioned parts interconnected. As shown in Figs. 4 and 5, the latch-tongue 134 has two flexible arms 135, forming a bifurcated end in which the stem 133 is located. Each of said flexible arms has at its end a small hook 136 adapted to project respectively into the transverse hole 137 of said stem to prevent the tongue 134 from becoming disconnected. The small hooks 136 are enabled to enter the transverse hole 137 by virtue of the reflex action of the arms 135, upon completion of the assembly operation. As revealed in Figs. 6 and 8, the stem 135 embodies two oppositely lying axial grooves 138, made of such width as to permit the tumbler-support 76 to be rotated freely over the small initial angle 139 or 140 (Figs. 2 and 6), without thereby effecting any appreciable angular movement in the latch-tongue 134 when it is in connection with a latch-mechanism as exemplified in Fig. 14.

The limited number of parts of the latch-mechanism, illustrated in Fig. 14, are shown in dotted lines with the exception of the hub-member 141 which forms an integral part with the follower 142 whereby the bolt 143 may be operated when the connected latch-tongue 134 is rotated over a definite angle by means of the key-operated tumbler-support 76. The hub-member 141 is shown provided with an outcut 144 made sufficiently large to permit free angular movement to be effected to a small extent in the latch-tongue 134 which projects into said outcut; accordingly, it will be apparent that means may be embodied in both the latch-mechanism and the tumbler-mechanism, or in each one separately, for allowing the tumbler-support 76 to be rotated over the small initial angle as shown in

Fig. 2, without communicating during such time any movement to the latch-mechanism of the lock.

In Fig. 6 and 8, the stem 133 of the tumbler-support 76 is shown carrying a bolt-operating device 145 of modified form, which may be employed in place of the latch-tongue 134 if a bolt-mechanism other than that shown in Fig. 14 is desired to be operated by means of the same tumbler-mechanism. As shown in the drawing, the bolt-operating device 145 embodies a projecting operating pin 146, adapted for operating the bolt 147 (Fig. 8) in any suitable manner as known to those skilled in the art.

The rear-closure for the tumbler-mechanism illustrated in Fig. 8 is shown made somewhat different from the aforescribed rear-closure 93, which in Fig. 4 is shown embodied with the lock-housing. In the device of Fig. 8, the rear-closure 20 of the housing forms an integral part with the plate 148 which is adapted to provide the closure for the housing 149 of the bolt-mechanism shown in dotted lines. The plate 148 includes the extensions 92A for holding the barricading ring 90 in 25 assembled position when the lock-housing 77A (shown in dotted lines) is connected to the plate 148. The slightly modified form of the lock-housing 77A is shown secured to the plate 148 by means of the screws 150, which also serve to hold the separate plate 151 in assembled position so that the rotatable tumbler-support 76 may be retained inside the lock-housing 77A. The thin flat washer 152, shown supported on the stem 133 is adapted to lessen during operation of the device 30 the frictional resistance between the inside face of the rear-closure for the lock-housing and the face on the rear-end of the tumbler-support 76.

The rear-closure 93 shown in Fig. 4 embodies a few constructional features in addition to those 40 already mentioned. As shown in the drawing, the peripheral section 153 of the closure 93 is provided with screw-threads to enable the device to be connected to a suitably constructed housing of a latch-mechanism. The rear-closure 93 is shown threaded into the housing 77; and for permanently securing the closure 93 in assembled position, there is a small screw or pin 154 shown inserted through a hole in the flange of the rear-closure 93, so as to project into the hole 155 (Fig. 11) in the threaded wall-section 156 of the lock-housing 77. The rear-closure shown in connection with the device of Fig. 4 may of course be 45 made without embodiment of the heavy threaded flange 153. For instance, a simple cup-shaped rear-closure may be incorporated, such as may be 50 economically made from sheet metal in a power press with a drawing die.

It is noteworthy that the present invention embodies a mechanical organization of such character that the operativeness of the lock is not 55 affected if the key-hole shutter is omitted from the construction; the elimination of the said shutter would merely deprive the lock of its maximum security; the last mentioned factor may, however, not always be of major consideration. If that be the case, and if a slight reduction in the cost of the manufactured article is desired, then the three elements of the shutter device, namely the shutter 75, the spring 115 and the ball 117 may be eliminated from the lock-construction; as well 60 as the washer 152 and also the latch-tongue 134, provided the stem 133 is suitably formed to serve as an operating member in direct connection with a latch-mechanism. Thus, the complete lock-unit, exclusive of the key-hole shutter, would 65

comprise no more than 12 simple and easily assemblable parts. Furthermore, the spring 84 adapted for co-action with the five tumblers, is of such construction that it is not liable to suffer wear or to go out of order through prolonged use of the lock; nor is there any appreciable wear liable to occur on the engaging parts between the tumblers and the key while the latter is moved into or out of the lock-mechanism. It will be apparent that the lock embodying the present invention can be master-keyed in a simple manner by providing more than one gate on one or more of the tumblers.

Modification of lock-mechanism including a key-hole shutter

The modification of the invention which will presently be described, is illustrated in Figures 15 through 25. The rotatable tumbler-support is in this particular device indicated by the reference character 76A, and is shown in Fig. 15 completely assembled inside the lock-housing 71A. While the rear-closure of the housing is shown in the form of a permanently secured flat disk 93A, having a centrally disposed hole 157 wherein the latch-tongue 134A is revolute. The tumbler-support 76A, comprising the cylindrical shell 158 and the tumbler-frame 159, has at its rear-end a cavity 160 (Figs. 23 and 24) adapted to receive the shouldered rear-end of the latch-tongue 134A; the two shoulders 161 (Fig. 24) being provided on the latch-tongue 134A to enable it to be retained in assembled position on the tumbler-support with co-operation of the disk 93A of the lock-housing. As shown in Fig. 24, the cavity 160 is of such form that the latch-tongue 134A is compelled to rotate with the tumbler-support 76A only after the latter has completed its initial angular movement during which the shutter 75A is moved to close the key-hole 85A of the tumbler-support in substantially the same manner as in the device of Fig. 1.

The barrier 90A, whereby the tumblers of the lock may normally be intercepted, is shown made in the form of a sector, as best seen in Figs. 16 and 22; said sector is secured in a slot of the housing 71A (Figs. 15 and 16) so that the spaced-apart barrier-elements 162 of the sector project to the inside of the housing 71A, and into the path of the projecting portions of the tumblers, as clearly indicated in Figs. 16 and 22.

The five tumblers, indicated respectively by the reference characters 79B, 80B, 81B, 82B and 83B, are fashioned from comparatively thin sheet metal, and are so supported on the frame 159 that they may be individually shifted back and forth within definite limits inside the lock-housing 71A. The tumbler 81B is provided with a projection 100A (Figs. 20 and 23) at its front edge; the said projection 100A being adapted to enter the depression 98A (Fig. 15) on the shoulder-section 99A of the housing 71A, whenever the key-hole 85A (Fig. 16) of the shell 158 is in alignment with the similarly formed key-hole 97 (Fig. 15) of the lock-housing 71A. Each of the five tumblers embodies a spring-engaging member 163 (Fig. 23), adapted to project into a rearwardly extending hole of the tumbler-frame 159; there being five holes made in said frame as shown in Fig. 22; each hole containing a cylindrical spring 164 (Fig. 23) adapted for urging its engaging tumbler forwardly in the direction of the key-hole of the lock. In conjunction with each of said holes, there is a slot 165 provided in the frame 159; each slot extends rearwardly only far enough to enable the lower edge of the corner-

section 166 (Fig. 23) of the respective tumblers to rest on the flat face 167 of the tumbler-frame 159; thus each tumbler is provided with a suitable path for its spring-engaging member 163 during operation of the device. In Figs. 20 and 23 the tumblers are shown held in a normal position by means of the respective cylindrical springs, so that the barrier-elements 162 of the sector 90A may intercept the tumblers after a small rotative movement has been effected in the tumbler-support 76A; the latter may be rotated beyond the small initial angle only when the respective gates 89 (Figs. 20 and 23) of the tumblers are moved by means of the correct key into alignment with the barrier-elements 162, as shown in Fig. 15.

The tumbler-frame 159 is shown embodying two forwardly extending members 168, adapted for holding the five tumblers in proper position while the shell 158 is being connected to the tumbler-frame 159.

For the accommodation of the projecting sections of the five tumblers, as best seen in Figs. 16 and 22, there is an outcut 169 (Fig. 17) made in the cylindrical wall of the shell 158; the open rear-end of the outcut 169 is adapted to engage a projection 170, located in the annular groove 171 of the tumbler frame 159; the groove 171 providing a seat for the open end-section of the shell 158 when it is in assembled position. There are additional securing devices shown provided in the form of two spaced-apart projections 172 (Fig. 21) on the front-end of the tumbler-frame 159; these projections are adapted to fit respectively into the spaced-apart depressions 173 (Figs. 18 and 25) disposed in the front-wall of the cylindrical shell 158.

The key-hole shutter 75A, shown embodied with the particular tumbler-mechanism of Fig. 15, is adapted to function in the same manner as hereinbefore described in connection with the mechanism of Fig. 1, viz., when the correct key (Fig. 19) is inserted into the lock, and is then rotated with the tumbler-support 76A, it causes the sideways moving shutter 75A to enter with its inner end-section into the slot 119 (Fig. 19) of the key 86A while the opposite end of the said shutter is forced out of the outcut 114 disposed on the shoulder-section 99A of the lock-housing 71A.

Certain constructional elements of the key-hole closing mechanism, incorporated with the device of Fig. 15, are of modified form; for instance, the spring-action in the shutter 75A is effected by means of a blade-spring 115A, which engages with its forward end a shoulder-section 114 (Figs. 20 and 22) of the said shutter, so that the latter may be urged into the outcut 114 of the housing 71A whenever the tumbler-support 76A assumes its normal position, as indicated in Fig. 16. The flat piece of material from which the spring 115A is formed includes the two extensions 115 (Fig. 21), adapted to fit into a depression of the tumbler-frame 159 to enable the spring 115A to be properly held in assembled position with aid of the cylindrical wall of the shell 158. The deep groove 176 (Figs. 21 and 23), forming part of the depression in which the spring 115A is seated, provides the necessary room for the spring-action of the device.

On the front-end of the tumbler-frame 159 is made a depression 177 (see Figs. 21, 22 and 23) wherein the shutter 75A is movably supported; the front-face of the said shutter is adapted to

engage the inner face of the front-wall 178 of the assembled shell 158, thus maintaining the shutter 75A in operative position in said depression 177. As shown in Fig. 18, there is a suitable outcut 179 made in the cylindrical wall of the shell 158 for accommodating the end-section of the shutter 75A. The front-wall 178 of the shell 158 embodies an inwardly projecting wall-section 180 (Figs. 18 and 25) whereby the tumblers may normally be held on the tumbler-frame 159 in the position as indicated in Fig. 20, where the shutter 75A may be seen arranged in front of the tumblers; a similar view is presented in Fig. 23.

For the projection 100A (Figs. 20 and 23) of the tumbler 81A, there is made a depression 181 in the wall-section 180 of the shell 158, so as to enable the operative part of the projection 100A to enter the depression 98A (Fig. 15) on the shoulder-section 99A of the lock-housing 77A, at a time when the key-hole 85A (Fig. 16) of the shell 158 is in alinement with the key-hole 97 (Fig. 15) of similar form on the lock-housing 77A.

If desired, the shell 158 may be constructed with embodiment of a hub-member 182, as indicated in dotted lines in Fig. 17 and 18; the said hub-member being adapted to revolvably project into the center-hole 126A (shown in dotted lines) made in the front-wall of the lock-housing; an arrangement of such character permits the neck 121A of the key 86A to be made comparatively wide, as suggested in dotted lines in Fig. 19. Obviously, the hub-member 182 of the shell 158 should embody a suitable slot, corresponding in outline to the form of the key-neck 121A, thus the slot in the hub-member 182 would constitute part of the key-hole of the lock. However, in order that the security of the lock may not be affected, the diameter of the hub-member 182 should measure somewhat less than the width of the key-hole shutter 75A.

Modification of the invention

The modified constructions described under this heading in the following paragraphs, are illustrated in Figures 26 through 49; and are exemplified in the drawing-figures without embodiment of a key-hole shutter, although a shutter of the form disclosed in Figs. 1 and 15 may be employed, if desired, in combination with any of the hereinafter described constructions, provided certain suitable alterations in details of construction are made therein so as to permit the incorporation of a key-hole shutter.

As pointed out in the preamble of this application, the main object of the present invention is the provision of means of such character that during a relatively small initial angular movement of the key-operable tumbler-support, operation may be effected in an operatively associated adjunctive device to prevent the tumblers from being movable relative one to another to the proper position while in close proximity with the stationary barrier-elements; the latter being normally disposed at a definite angular distance away from the normal position of the tumblers.

In Figs. 1 through 25, the said adjunctive device is shown in the form of a key-hole shutter of specific construction, whose operation may be effected while the tumblers of the lock are carried on a rotatable supporting frame toward the stationary barrier-elements. On the other hand, in the constructions of Figs. 26 through 49, and several others in this application, the said ad-

junction device is shown in the form of a mechanism of such character as to enable each and all of the tumblers to be locked in a fixed position in relationship with respect to one another while the tumbler-support of the lock is being rotated over a small angle away from its normal position. Thus, the basic elements, which afford the operation of one or another type of adjunctive device to be effected for the stated purpose, are embodied principally in the spaced arrangement of the stationary barrier-elements, as applied in the several species of construction of the invention, so that the tumblers must first be carried on the tumbler-support over a definite angular distance in order to bring the interceptable parts or the respective gates of the tumblers into close proximity with the stationary barrier-elements of the lock.

One of the specific constructions of the invention embodying a tumbler-interlocking-device is illustrated in Figs. 26 through 38, which will be fully described before proceeding with the detailed description of other similar constructions.

The tumbler-support as shown in Figs. 27 and 30, comprises three interconnected parts; the main part, on which the cylindrical springs and the tumblers are mounted, is indicated by the reference character 183 (Fig. 32); to the front-end of said main part 183 is connected a hub-member 184 (Figs. 27, 30 and 33), shown in the form of a cup-shaped element which includes the short cylindrical central projection 182A having the key-hole 85B; said projection 182A fits loosely into the center hole disposed in the front-wall of the lock-housing 77B (Figs. 26 and 27). The key-hole 85B of the tumbler-support extends to the left and right of the periphery of the projection 182A (Fig. 33), so as to enable a key-way to be formed in the front-wall of the housing 77B by the respective outcuts 97A. The key-hole 85B is disposed slightly off center, so that after the tumbler-support 76B has been rotated over an angle of 180° it carries the key-hole 85B to the position relative to the outcuts 97A of the housing as indicated in Fig. 38; thus, until the tumbler-support is returned to its normal position, the shoulder-portions on the neck 121B of the key prevent the latter from being pulled out of the lock.

To the rear-end of the tumbler-supporting member 183 is connected the member 185 (Fig. 30) for revolvably supporting the tumbler-support 76B inside the cup-shaped barricading member 90B; the latter is shown having a flange 186 resting on a shoulder of the housing 77B to which said barricading member 90B is permanently secured. There is a second flange 187 (Fig. 27) formed on the member 90B, this flange serves to retain the tumbler-support 76B inside the lock-housing 77B by engaging the shoulder-section 188 (Fig. 31) of the member 183. However, the flange 187 is principally provided for the embodiment of the spaced-apart barrier-elements, indicated respectively by the reference characters 106A, 107A, 109A and 110A (Figs. 31 and 35). It will be noted that these barrier-elements are arranged in a fashion similar to those of the barricading ring 90 shown in Fig. 9. As revealed in Fig. 35, the barrier-element 106A is arranged so as to enable it to intercept the tumbler 80C at the same time when the tumbler 80C is moved in abutment with the barrier-element 107A, that is, if the gate 89 (Figs. 30 and 36) of the respective tumblers is not in alinement with the flange 187 of the barrier-member 90B. The barrier-elements 109A

and 110A afford the tumblers 82C and 81C to be intercepted at one and the same time when the tumbler mechanism is rotated in a counter-clockwise direction.

The detailed constructional features of the tumbler-supporting member 183 may best be seen in Fig. 32. In association with each of the three holes 189 there is a slot 165A made to provide a suitable path of movement for the respective members 163A of the tumblers. Each tumbler embodies two sideways projecting supporting elements 190; the upper one being adapted to ride on the flat face 167 (Fig. 32) of the frame-member 183, while the other element 190 engages the face 167A disposed on the lower side of the holes 189; thus enabling each tumbler to be maintained in proper operative position on the frame-member 183. Additional supporting means for the tumblers are provided by the walls 191 of the outcut 192, which is made in the frame-member 183 for the accommodation of the tumblers, as shown in Figs. 28 and 31.

Each tumbler is shown embodying a toothed member 193, which forms part of the supplementary device adapted for interlocking the several tumblers relative to one another with co-operation of certain other operating elements incorporated with the barrier-member 90B. The toothed members 193 project into the outcut 194 (Figs. 31 and 32) of the frame-member 183; a similar outcut 98B (Fig. 35) is provided on the flange 187 of the stationary barricading member 90B; consequently the rotatable tumbler-support 76B may be prevented from being rotated away from its normal position, indicated in Fig. 31, as long as the tumblers are held by their respective cylindrical springs 164 in the forward position as shown in Fig. 30, because then a toothless portion 100B on the extreme rear-end of the respective members 193 lies in the path of certain edge-portions formed by the said outcut 98B. A careful examination of the last mentioned features will reveal that the same function, that is, the maintenance of the rotatable tumbler-support in its normal position, is accomplished by means of the tumbler-portion 100 when located in the depression 98 of the lock-housing 71, shown in association with the particular lock-mechanism illustrated in Figs. 1 through 14.

The ratchet-formed teeth 195 of the member 193 are arranged on the lower edge thereof, rearwardly of the toothless portion 100B, and are adapted severally to engage the beveled edge 196 of the flange 187, whenever the tumbler-support is rotated to the left or right after the tumblers have first been moved back to a lesser or greater extent, thus enabling all of the tumblers to be interlocked in any particular position relative to one another before the interceptable parts of the tumblers are carried into abutment with any stationary barrier-elements of the lock-housing. It follows therefore that if all of the tumblers are moved backward to the proper position, as may be accomplished with the correct key before the said interlocking operation is effected, then it enables the lock to be operated; but such operation is not possible if one or more of the tumblers are not first moved to the proper position, because any tumbler whose gate is out of alignment with the barrier-elements of the device may be intercepted thereby; obviously, no adjustment in the position of the tumblers can be made until the tumbler-support 76B has been returned to its normal position to permit the toothed section of the tumbler-member 193

to be released from the beveled edge 196 of the barricading device 90B.

The rear-member 185 (Figs. 27 and 30) of the rotatable tumbler-support 76B may be provided with any suitable driving device, adapted for the operation of an interconnected latch-mechanism. In the form shown, the said rear-member 185 embodies an eccentric pin 197, of which a sectional end-view is presented in Fig. 34, where the pin 197 is shown operatively engaging a spring-bolt 198; the latter forming part of a padlock mechanism, indicated by the reference character 199. The large circle, shown in dotted lines in Fig. 34, suggests the position of the rear-member 185 of the tumbler-support 76B when incorporated with a padlock; and the two small circles, also shown in dotted lines, indicate respectively the position to which the eccentric pin 197 may be rotated toward the left or right from its normal position by means of the key-operable tumbler-mechanism for effecting unlocking operation in the spring-bolt 198.

The lock-construction illustrated in Fig. 39 through 49, which will presently be described, is in principle of operation very similar to the construction revealed in Figs. 26 through 38; there exist, however, in these two constructions certain noteworthy differences in the arrangement of the operating parts, as will be elucidated in the following detailed description.

As shown in Figs. 40, 41 and 42, the rotatable tumbler-support 76C (Fig. 41) embodies a frame-member 183C having five tumblers; the two tumblers which are shown operatively supported on the upper side of said frame-member (viewing Fig. 41) are indicated respectively by the reference characters 80D and 82D; while the three tumblers held in operative position on the lower side are indicated respectively by the reference characters 79D, 81D and 83D. Each tumbler embodies a spring-engaging member 163B movable within definite limits in a suitable slot which is made conjunctly in two oppositely lying sides of the hole wherein the cylindrical spring 164 is located for effecting the necessary spring-action in the particular tumbler it engages. On the said member 163B of each tumbler is formed a forwardly projecting annular member 201, fitting loosely into the hole of the cylindrical spring 164, thus enabling the forward end of the respective tumblers to be properly supported. At the rear-end the two upper tumblers are movably supported between the cylindrical wall 200 of the barricading member 90C and the flat face 167C of the frame-member 183C; the other three tumblers are similarly supported at the rear-end between said cylindrical wall 200 and the second flat face 167C formed on the lower side of the frame-member 183C. Furthermore, the outcuts 192A and 192B of the frame-member 183C (Fig. 43) respectively provide supplementary supporting means for the tumblers accommodated therein.

To the front-end of the frame-member 183C (Figs. 40 and 41) is connected the cup-shaped hub-member 184A, having a relatively small cylindrical portion 182B with its key-hole 85C (Fig. 39) adapted to revolvably project into the central hole of the front-wall on the lock-housing 71C; on the peripheral edge of said central hole of the housing 71C is made a small outcut 97B (Fig. 39) arranged so as to merge into the key-hole 85C of the said member-portion 182B whenever the tumbler-support 76C is disposed in its normal position to permit the key 85C to be inserted into the lock or to be pulled out therefrom only then

when the tumblers of the mechanism are free to be shifted one relative to another, as indicated in Figs. 40 and 41. The form of the key 86C shown in Fig. 43, has a shoulder-portion 123A on the neck 121C adapted to prevent the key from being pulled out of the lock, unless the said shoulder-portion 123A is disposed in register with the out-cut 97B of the lock-housing. As best seen in Figs. 41 and 42, the frame-member 183C further embodies a key-way 85D which is in effect merely a continuation of the key-hole 85C. However, the said key-way 85D may be regarded as being that part of the key-hole wherein the key-engaging portions of the tumblers are arranged in series as indicated in Fig. 41; thus, when the correct key is inserted as far as permitted into the key-hole 85C, the five tumblers are urged one relative to another by the notched key-edge 88B to the operative position shown in Fig. 47, hence allowing the tumbler-support 76C to be subsequently rotated in a clockwise or counterclockwise direction beyond the stationary barrier-elements of the barricading member 90C.

On the flange 187A (Fig. 48) of the barricading member are made the two outcuts 98C and 98D, the latter being disposed diametrically opposite the former. In the upper outcut 98C are normally held the interceptable edge-sections of the two tumblers 80D and 82D; while in the out-cut 98D on the lower side are normally located the interceptable edge-sections of the three other tumblers. Now, as long as the tumblers are disposed in the foremost position, as shown in Fig. 40, they cannot be carried in an angular direction away from the outcut 98C and 98D, because the toothless portion 100C of each tumbler is in position to inhibit such movement. Hence, all of the tumblers must first be moved backwards to a definite extent in order to enable the tumbler-support 76C to be rotated far enough to carry its tumblers very close to the stationary barrier-elements of the lock. But while the tumblers are carried over the above mentioned initial angular distance, they all become interlocked in the particular position relative to one another to which the tumblers were moved before said angular movement in the tumbler support has been effected.

The spaced-apart barrier-elements with which the respective gates 89 of the tumblers must be brought into alinement to afford extensive rotative movement to be effected in the tumbler support 76C, are indicated respectively by the reference characters 106C and 109C for the two tumblers on the upper side, and 107C, 110C for the three tumblers on the lower side of the frame-member 183C. Each of said barrier-elements is formed at the end of a beveled edge-portion, indicated respectively by the reference character 196A; these beveled edge-portions are arranged so as to enable a toothed section of any and all tumblers to be engaged thereby in order to prevent the tumblers from being shifted relative to one another after having been carried in an angular direction over a limited distance away from their normal angular position.

In the device of Fig. 47 the gate 89 of the respective tumblers is made on the same edge on which the teeth 195 are formed. For the preservation of maximum security in a lock having tumblers of this particular construction, the teeth 195 may be spaced wider apart than shown in the drawing, so as to be equal in width to that of the gate 89; but if that is not done, then some other effective means may be incorporated in the

tumbler-mechanism for the accomplishment of a similar purpose, viz., to prevent the proper position of the individual tumblers to be determined by feel with aid of a makeshift instrument manipulated from the outside of the lock. Accordingly, the above noted object may be achieved by arranging at a small suitable distance in rear of each of said beveled edge-portions 196A another beveled edge-member 202, as clearly shown in Figs. 47 and 48. For the purpose of description it will suffice to consider the particular arrangement of the beveled edge-member 202 in rear of the barrier-element 107C. The tooth-engaging portion of the edge-member 202 lies on a circumference equal to that of the tooth-engaging portion of the member 196A in front of it, so that a tooth of any of the five tumblers may be brought into engagement with the beveled edge-member 202 at the same time while either another tooth or the gate of a tumbler is moved into engagement with the beveled edge 196A; thus even if the gate 89 is moved during attempted picking of the lock into engagement with one or the other of the two parallel beveled edge-members, there is no way of positively determining by means of a feeler where the gate of any particular tumbler is located relative to the stationary barrier-elements of the lock.

As shown in Fig. 40, the barricading member 90C is held with aid of its flanged rear-end 186A in fixed position on the lock-housing 11C. On top of said flanged rear-end 186A is secured the disk-shaped rear-closure 93B, in which the hub-member 203 of the tumbler-support 76C is journaled. Inside the cavity 160A (Fig. 47) of the said hub-member 203 is held the shouldered end of the latch-tongue 134B with aid of the fixed annular member 204 (see Fig. 40).

If this particular tumbler mechanism is desired to be incorporated with a padlock, as illustrated in Fig. 49, then the rear-section of the tumbler-support 76C may be modified so as to embody a suitable operating member 185A, provided with an eccentric bolt-operating pin 197. The rear-closure 93B is not needed, because in place thereof of the frame-member of the padlock in which the bolt 198 is located is adapted to retain the tumbler-support 76C in its assembled position inside the housing 205, which constitutes a part of the body-structure of the padlock.

If desired, the key for the operation of the lock-mechanism, embodying the present invention, may be made in two separate sections, as exemplified in Figs. 44, 45 and 46, to afford the key to be employed for the operation of the lock only when the section 206 of Fig. 44 is properly attached to the section 206B of Fig. 45, so as to complete the operating end 87A of the key. The end-section of the last described key, as revealed in Fig. 46, is shown to have a different outline than the key-hole 85C (Fig. 39); it being understood, however, that in practice the operating end of the key is always made to correspond to the form of the key-hole of the lock.

Additional modifications

Among the several distinguishing characteristics inherent in the two modified constructions of the invention, which will be described in proper order in the following paragraphs, may be noted the provision of means to enable interlocking operation in all the tumblers of the lock to be effected simultaneously during a small initial angular movement in the mechanism, irrespective of the angular direction in which the tumbler-support of the device is rotated.

In the construction revealed in the drawing-figures 50 through 59, the particular object mentioned in the preceding paragraph, is accomplished with aid of a pivoted lever 207, adapted to carry a barrier-element 208 which is normally held at a small distance away from the engageable edge-sections 193E (Fig. 57) of the five tumblers (Fig. 52), the latter being operatively supported on the rotatable tumbler-support 76E. In Fig. 52, the five tumblers 79E, 80E, 81E, 82E and 83E, may all be seen in assembled position on the frame-member 183E, which embodies suitable pathways to enable shifting movement to be effected within definite limits in said tumblers relative to one another with co-operation of a cylindrical spring 164E associated with each tumbler in the particular fashion as illustrated in Fig. 57.

On the forward end of the said frame-member 183E is attached the cup-shaped hub-member 184E, having its key-hole 85E arranged so as to be normally held in register with the two separate outcuts 97E (Figs. 50 and 56) made in the front-wall of the lock-housing 77E; the arrangement of the key-hole 85E relative to the said outcuts 97E being similar as in the device of Figs. 26 and 38, viz., to permit the key of the lock to be pushed in or to be pulled out only then when the tumbler-mechanism is disposed in its normal position. As shown in Fig. 57, the hub-member 184E has on its flat front-wall a projection 209 fitted into a depression 210 on the front-end of the frame-member 183E, thus providing the necessary securing means to prevent angular displacement of the hub-member 184E relative to said frame-member 183E; the former and the latter constituting the tumbler-support 76E.

Another detailed feature of the hub-member 184E may best be examined in Fig. 54; the front-wall of said hub-member has two holes (not shown) arranged so that the forwardly projecting annular member 201E of the tumbler 83E (Fig. 52) may pass through one of said holes at the left, and a similar annular member of the tumbler 79E may pass through the other hole at the right. Both said projecting annular tumbler-members being made of such length as to enable them to respectively project to the extent shown in the drawing into the holes 98E (Figs. 54 and 56) in the front-wall of the lock-housing 77E while the tumbler-support 76E is disposed in its normal position. Accordingly, rotative movement in the tumbler-support 76E may be effected only after the annular tumbler-members 201E are moved out of said holes 98E; but, as is self-evident, all of the tumblers must be shifted backwards to the proper position relative to one another and relative to the barrier-element 208 to permit the lock-mechanism to be operated.

The hub-member 184E further embodies in its cylindrical wall an outcut 211 (Fig. 54), which forms part of a similar outcut 212 (Fig. 57) made in the peripheral section 213 of the frame-member 183E; the above-mentioned outcut is adapted to guide the up and down movement of the lever 207 at its front-end, which is held in engagement with a short cylindrical spring 115E, tending to swing the said lever outwardly, and normally maintaining it in the angular position shown in Fig. 57.

On the rear-end of the frame-member 183E is made a suitable fulcrum-cavity (Figs. 55 and 57) for journalily supporting the shaft 214 of the lever 207; said lever shaft being retained on its fulcrum with aid of the contiguous wall of the rear-

closure 93E when the latter is connected to the lock-housing 77E by means of the screws 150E, or some other form of securing devices. As shown in Figs. 51, 54 and 57, the frame-member 183E has a relatively large cylindrical portion cut away, thus forming the fulcrum-member 215 at the rear, and the member 213 at the front where the compression spring 115E is located; in between these two members is formed the flat wall 216, beneath which the five tumblers are accommodated. In said flat wall 216 is made a transverse slot 217 (Figs. 54 and 57) through which the barrier-element 208 of the lever 207 is permitted to move into the path of the tumblers.

The means for accomplishing the movement in the barrier-element 208 comprises the outcut 114E in the peripheral wall of the lock-housing 77E, wherein the cam-member 218 of said lever is normally held by force of the compression spring 115E; said outcut 114E has two operating edges 219, one at the left and another at the right (viewing Fig. 56) so that when the tumbler-support 76E is rotated away from its normal position, in either a clockwise or a counter-clockwise direction, it forces the cam-member 218 out of said outcut, thus urging the lever 207 inwardly to carry its barrier-element 208 through the slot 217 into the respective gates of the properly positioned tumblers while held in engagement with the notched operating end of the correct key; the tumbler-support 76E may then be freely rotated, and when it is returned to its normal position, it permits the spring-operated lever 207 to swing back, thus carrying the barrier-element 208 out of the path of the tumblers.

From the foregoing description it is evident that the particular construction of Fig. 57 embodies an adjunctive device adapted to carry the barrier-element of the mechanism toward or away from the tumblers while the tumbler-support of the lock is being rotated over a definite angle; whereas in the mechanical arrangement disclosed in other species of the present invention, the spaced-apart barrier-elements are not movable in such manner.

Assuming now, for the purpose of example, that some form of makeshift instrument is employed in an attempt to operate the lock; in that case it is necessary to first push the two tumblers 79E and 83E far enough back to urge the annular tumbler-members 201E out of the housing-holes 98E; leverage may then be applied for rotating the tumbler-support 76E over a small distance away from its normal position; while this is done; it ultimately causes the barrier-element 208 to be carried by the downwardly swinging lever 207 into engagement with the upper toothed edge-section 193E of all the tumblers, or at least some of them, depending to what particular position each tumbler is moved before such interlocking operation is effected. The barrier-element 208 has a plurality of teeth made lengthwise on its edge, thus enabling it to grip securely any tumbler with whose toothed edge it is brought into pressure-engagement. Now, in order to make it impossible to determine by feel with the aid of a makeshift instrument whether or not the gate of any tumbler is moved into alignment with the barrier-element 208, there are several outcuts 195E made on the upper edge of the respective tumblers (see Figs. 57 and 58); each of said outcuts 195E is made of exactly the same width as the gate 89, so that there is no way of knowing whether the gate or one such outcut 195E is in alignment with the barrier-element 208 in

case some tumbler is not held gripped on its edge-portion having the small teeth. The additional outcrops 195E are considerably less in depth than the gate 89, so that the lever 207 may not be forced out of the outcut 114E of the housing 71E even if by some remote chance the tumblers should be urged relative to one another to a position to allow the barrier-element 208 to enter one or the other of said additional outcrops 195E of the tumblers.

The lever 207 may further be adapted for the operation of a key-hole shutter of the type illustrated in Fig. 23, provided the front-part of the tumbler-support 76E of Fig. 51 is suitably constructed for the accommodation of such a shutter. For the purpose of example it is considered sufficient to indicate in Fig. 58 an extension on the front-end of the lever 207 adapted for the connection of a pin 75E, shown in dotted lines; thus suggesting the manner of operatively associating with the lever 207 a key-hole shutter or some other form of obstruction movable into the key-hole 85E while the barrier-element 208 of the lever 207 is carried toward the tumblers of the mechanism during initial angular movement of the tumbler-support 76E.

On the operating part 87E of the key 86E (Fig. 53) is indicated in dotted lines the position of the hole 119E through which the free end 220 of the pin 75E may move, in a manner similar as the shutter 75A in the device of Fig. 20. Considering further the key 86E of Fig. 53, there is shown in dotted lines the full blank of the operating part 87E, outlining that particular section on which the irregular tumbler-engaging notches 88E may be cut, as desired, down to the limit indicated by the section-line 221.

As shown in several of the drawing-figures, the frame-member 183E embodies at its rear-end a stem 133E, which projects through the hole 157 of the rear-closure 93E to the outside thereof, where a suitable form of bolt-operating device may be connected to said stem. In Figs. 51 and 59, a pinion 145E is shown fixed to the stem 133E, which pinion is adapted for the operation of the mechanism disclosed in Fig. 59; this particular mechanism is of such construction that two separate key-locks have to be operated simultaneously to enable operation to be effected in an interconnected bolt. To achieve this end, a frame 222 is provided on which two lock-units 223 and 224 are mounted at spaced relation with respect to each other. Each lock-unit carries on its stem 133E a pinion 145E, and both pinions are being held in driving engagement with the rack 225; the latter is shown embodying an operating pin 146E, which is made to project into the outcut 226 of the sideways shiftable member 227, whereby a bolt (not shown) may be moved in or out of locking position. The frame 222 includes the upper flange 228 for properly guiding the rectilinear movement of the toothed rack 225 during rotative movement of the two pinions 145E while two separate keys are employed for the simultaneous operation of the two operatively interconnected locks 223 and 224. The member 227, forming part of the bolt-device, is movably supported on the lower flange 229 of the frame 222.

On the mid-section of the bolt-member 227 is provided a slot 230 through which the holding-pin 231 is made to project; the said pin being fixed to the frame 222 in order to enable the bolt-member 227 to be held in operative position with aid of the large pin-head 232. In the draw-

ing is further shown a section of an operatively associated detent-member 233, adapted for up and down movement through the hole 234 in the upper flange 228 of the frame 222. Another hole 235 is shown made in the upper edge of the rack 225; said hole being so positioned as to be movable into register with the first mentioned hole 234 of the said flange 228 at a time when the rack 225 is shifted to the right for urging the interconnected bolt to locking position by means of the rack-operated member 227. Thus, when the said rack is moved to its full extent to the right, it permits the detent-member 233 to be moved down into the hole 235 of the toothed rack, in which case the bolt-operating rack may not be operated by means of the key-locks unless the detent-member 233 is first moved back to its normal position. The above described movement of the detent-member 233 may be effected with aid of an additional lock; or, if desired, with aid of a suitable timing mechanism, adapted for moving the interconnected detent-member 233 out of rack-engaging position after a predetermined time-period.

25 The outer form of the lock-housing and its connecting means may of course be fashioned as desired, according to the particular requirement of the mounting-frame to which the lock-unit is intended to be attached. For example, the housing of Fig. 51 may be provided with a shoulder 236 at its front-end, as indicated in dotted lines in Fig. 54; or a receding shoulder 236A may be formed on the lock-housing as indicated in dotted lines in Fig. 57.

30 35 The modified lock-mechanism illustrated in the drawing-figures 60 through 71, which will be described in the following paragraphs, is shown accommodated inside a hollow shank of a door-knob 237 (Fig. 60), or a handle 237F; the latter being shown, partly broken away, in Figs. 61, 62 and 63.

40 Accordingly, the said hollow shank 71F may properly be regarded as being the lock-housing, which in this particular instance is revolvably supported with its rear-end in the socket of the bracket 238, as shown in Fig. 60, so that the housing or shank 71F may serve to effect operation in an interconnected latch-mechanism, under locking control of a device operatively associated with the key-operable mechanism in said shank 71F. As shown in the drawing, the key-operable mechanism of the present invention is adapted for the operation of a simple device whereby the shank 71F may be locked to or unlocked from the bracket 238; the means for accomplishing this end includes the bolt-operating device 145F, fixed to the rear-end of the stem 133F; the latter forming an integral part with the rotatable tumbler-support 76F (Fig. 60), which is retained in the hollow shank 71F with aid of the relatively thick rear-closure 93F, shown resting on the flange of the cup-shaped barricading device 90F for holding the latter in fixed position on the shank 71F when said rear-closure 93F is rigidly secured thereto. The shank 71F is retained in the socket of the bracket 238 with aid of the bolt-operating device 145F which is shown engaging the outside face of the bottom 239, formed by said socket of the bracket 238. In 45 50 55 60 65 70 75 80 85 90 95 100 said bottom 239 is made a large center hole through which the stem 133F of the tumbler-mechanism projects, and at a small radial distance from said center hole is made a smaller hole for loosely retaining a locking pin or bolt 240 which is adapted for movement with one end-

portion into and out of the hole 241 made in the rear-closure 93F. As shown in Figs. 60 and 71, the bolt-operating device 145F has a pin-engaging segment 242 which embodies two spaced-apart beveled edges 243 (Fig. 61), so as to enable the device 145F, while disposed in the angular position shown in Fig. 61, to retain the pin 240 in locking position inside the hole 241 of the rear-closure 93F to inhibit angular movement in the shank 71F; but whenever the said bolt-operating device 145F is rotated away to a definite extent from such locking position, it allows the pin 240 to be urged out of the hole 241 of the rear-closure 93F by the reflex action of the operatively connected curved spring 244 (Fig. 61) as soon as one or the other of said beveled edges 243 is moved out of engagement with the pin 240, which thereafter is held during its unlocking position in abutment with the face of the other thin segment 245 of said bolt-operating device 145F; the said face of the thin segment 245 being disposed at a suitable distance away from the outside face of the socket-bottom 239 to afford the pin 240 to be moved to unlocking position in the manner specified above.

The tumbler-mechanism of the device of Fig. 60 is so constructed that the key may be withdrawn from the lock after having been rotated over an angle of 180° from either one of the two normal positions in which the tumbler-mechanism may be maintained; thus enabling the above described bolt-operating device 145F to be left in either a locking position or an unlocking position. If, therefore, the tumbler-support 76F is rotated in either a clockwise or a counter-clockwise direction over an angle of 180° away from the angular position shown in the drawing, it carries the thin segment 245 of the bolt-operating device 145F to that side where the pin 240 is located, thus causing the shank 71F to be unlocked by virtue of the spring-operated outward movement of the pin 240, so that then the shank 71F may be rotated over a limited angle for effecting operation in an operatively connected latch-mechanism, such as may embody a beveled bolt for securing a door in shut position. In Fig. 61 is shown in dotted lines a fragment of a bolt-member 246, adapted for the operation of a beveled bolt (not shown) of usual construction. The bolt-member 246 is shown including an element 247 held in driving engagement with the rear-end of the shank 71F, and is made to project through the curvilinear slot 249 in the bottom 239 of said bracket 238.

If instead of the handle 231F, a knob 237 (Fig. 60) is employed for the operation of the member 248, then the slot 249 may be made longer than shown in the drawing, so as to extend over a suitable distance to the left and right of the operating member 248; thus enabling a bolt of a latch-mechanism to be operated while the knob 237 is rotated over a limited angle either to the left or to the right. For such bolt-operation, the operating member 248 may suitably be modified to include a bolt engaging device 250 (shown in dotted lines in Fig. 60) adapted for the operation of a latch-mechanism similar to that illustrated in Fig. 14. On the other hand, if a dead bolt 147, of the type shown in Fig. 8, is desired to be operated, then a pin 146F (Fig. 71) may be secured to the bolt-operating device 145F so as to enable an operatively connected dead bolt to be thrown to locking or unlocking position with a half-turn of the tumbler-support 76F. Hence,

the particular lock-mechanism illustrated in Figs. 60 and 61 may be employed, as desired, for the operation of a dead bolt of the above mentioned type, either with or without embodiment of the locking pin 240, whereby locking operation may be effected separately in connection with the shank 71F. With the above consideration in view, there is provided a mechanical arrangement in connection with this particular species of the present invention to afford the key-operable tumbler-mechanism to be normally maintained in its housing in at least two different angular positions.

In Fig. 64 is shown the key 86F, which is adapted for the operation of the tumbler-mechanism illustrated in Figs. 60, 68, 69, 70 and 71. While in Fig. 62 may be seen the key-hole in the front-wall 251 of the housing or shank 71F; said key-hole comprises two relatively narrow outcuts 97F and 97G, arranged diametrically opposite each other and merging into the round center hole 126F, which is shown having two wards 124F. On the inside of the housing-wall 251 (Fig. 63) is made a bearing-socket 252 in which the revolute hub-member 184F of the rotatable tumbler-support 76F is accommodated. Said hub-member 184F has a key-hole 85F, corresponding in outline to the key-hole of the housing 71F; it should be noted, however, that the key-hole of the hub-member 184F embodies merely one narrow outcut 253, which may be carried into register with either one of the aforementioned outcuts 97F or 97G of the lock-housing 71F. The said outcut 253 of the hub-member 184F extends rearwardly only to a small distance, just enough to permit the accommodation of the beard 254 of the key 86F, shown in Fig. 64. It will therefore be obvious, if the outcut 253 is in alignment with the outcut 97F of the housing-wall 251 (Fig. 62) that then the beard 254 of the key 86F may enter only through the said outcut 97F; but after the tumbler-support 76F is rotated a half-turn around from said first-mentioned position, it carries the outcut 253 of the hub-member 184F into register with the upper outcut 97G of the lock-housing 71F; in which case the key 86F may be inserted while its beard 254 is disposed on the upper side. The notched operating end 87F of the key 86F is shown provided with an axial bore 255 into which the centrally located pin 256 (Fig. 71) of the tumbler-support 76F may enter when the key is inserted into the lock.

In Fig. 63 are shown six cavities or depressions, arranged equidistantly on the front-wall 55 of the housing 71F; all six depressions are identical in form, one of which being indicated by the reference character 98F. Each of these depressions 98F is adapted for receiving the forwardly projecting end 100F of a tumbler; in Fig. 68 may be seen from the front the six tumblers which this particular modification of the invention is shown to embody. One of the tumblers, shown supported on the upper side, is indicated by the reference character 81F, and another tumbler, disposed on the lower side, is indicated by the reference character 81G; most of the detailed features of these two tumblers may be clearly seen in Fig. 71.

As shown in the drawing, the frame-elements 70 of the tumbler mechanism are of unusually simple construction, such as may be produced in quantity at a minimum cost in labor and material. Viewing Fig. 71, the central part of the tumbler-support 76F is fashioned from a piece of tubing 75 257, which embodies the key-hole 85F, in the

center of which is disposed a relatively thin pin 256, held in position by the rod or core 258 which is secured inside the rear-section of said tube 257; the latter further embodying in its peripheral wall six slots 259, arranged equidistantly from each other in parallelism to form paths of movement for the respective tumblers of the device. Another cylindrical member 260, of larger diameter than the central tube 257, is joined at the fore-end of the latter as shown in Fig. 71; at said joined end is formed the hub-member 184F, adapted for revolvably supporting the tumbler mechanism on the front-wall of the lock-housing as hereinbefore stated. On the rear-end of said cylindrical member 260 is secured a holding plate 261, which comprises a tube-embracing sleeve 262 to form the hub-member for revolvably supporting the tumbler-support 76F in the central hole of the rear-closure 93F, as illustrated in Fig. 60. In the cylindrical wall of the member 260 are made six outcuts 263 (see Figs. 60, 68 and 70); each of the last mentioned outcuts comprises a tumbler-supporting slot extending from the front rearwardly to approximately half the length of the member 260, at which point said slot merges into a relatively large outcut adapted for the accommodation of the cylindrical spring 164.

All of the tumblers of the mechanism are of a construction similar to that of the tumbler 81F, whose detailed features will presently be described in association with certain operatively interrelated elements of the lock-mechanism. The lengthwise mid-section 264 (Figs. 68 and 71) of the tumbler 81F is made slightly thicker than its upper and lower edge-section, so as to form suitable shoulders whereby the tumbler may properly be supported in its path of movement on the tumbler-support 76F. The lower thinner edge 265 of the tumbler 81F projects through the slot 259 of the central tube 257 into the key-hole 85F, thus enabling the front-edge-portion 266 (Fig. 71) of said tumbler to be engaged by a notch-element 88F of the key 86F for the purpose of moving the tumbler backwards to its correct operative position. The upper tumbler-edge-section 267 (Figs. 68 and 70) is supported in the narrow outcut of the outer member 260, from which said edge-section projects outwardly to a small extent. This outwardly projecting edge-section 267 embodies the gate 86, and also several notches 195F, the latter being made of a depth only about half that of the tumbler-gate 86. At the rear-end is formed on the tumbler a spring-engaging member 268, adapted for supporting the front-end of the cylindrical spring 164, whose coils are shown supported on the wall of the central tube 257. The rear-end of the spring 164 is held in position by the connected plate 261 with co-operation of its inwardly bent member 269, so that the said spring may not become displaced during operation of the mechanism. The tumbler 81F, as well as all the other five tumblers, may normally be pushed back as far as permitted by the shoulder 270 (Fig. 71) of the core 258. As shown in Fig. 71, the slot 259 of the central tube 257 extends to a definite limit rearwardly of said core-shoulder 270, thus enabling the tumbler to be readily placed in its operative position before the core 258 and the holding plate 261 are assembled with the two parts of the tumbler-support shown in Fig. 70.

The essential operating elements of the barricading device 90F may best be seen in Fig. 68; and in order to avoid confusion of lines in the

drawing, the flared-out connecting elements 271 (Fig. 70) of the cylindrical member 260, and the holding-plate 261 of the tumbler-support are omitted in Fig. 68. It will be noted that the barricading device 90F is in certain respects similar in construction to the device 90C, shown in Fig. 48; however, in the barricading device 90F there are formed on the flange 187F six equidistantly located outcuts; one for each of the interceptable edge-sections of the respective tumblers in the mechanism. The particular operating elements of the outcut on the said flange 187F into which the upper edge-section 261 of the tumbler 81F is shown to project will presently be described in detail to offer a full understanding of the locking principles which this device embodies.

Referring now to the said outcut on the flange 187F: As seen in Fig. 68, there is formed a small radial edge or barrier-element 272 at the left, and at a short distance to the right thereof is formed a similar radial edge 272A; both said edges being normally disposed at a small angular distance away from the uppermost interceptable edge-section of the tumbler 81F, viz., at a time when its forwardly projecting portion 100F (Fig. 71) is held in the depression 98F (Fig. 63) of the lock-housing. To the left of said barrier-element 272, but somewhat closer to the center of rotation of the tumbler-support 76F, is formed another radial edge or barrier-element 109F; and at the right of the above mentioned edge 272A is likewise formed an edge or barrier-element 106F, which, like the edge 109F, extends radially close to the circumference of the cylindrical member 260, so as to be disposed in the path of the lowermost portions of the interceptable edge-section of the tumbler 81F. As a result of the particular arrangement of the aforementioned barrier-elements, there are formed two circumferential edge-portions, one at the left and another one at the right; these edge-portions are indicated respectively by the reference characters 196F, and they constitute the means for holding the tumbler 81F locked in position, to prevent it from being shifted axially relative to the flange 187F if one of the notches 195F (Fig. 71) or the gate 86 of said tumbler becomes engaged with either one of said edge-portions 196F during a small initial angular movement of the tumbler-support 76F. All the other tumblers of this particular device, as shown in Fig. 68, are associated with similar barrier-elements, and thus they embody individually operating principles similar to those described above in connection with the tumbler 81F. It will therefore be evident that all of the tumblers must be moved backwards to the proper operative position at one and the same time, that is to say, before said interlocking operation of the tumblers is effected during initial angular movement of the mechanism, in order to thereafter enable the tumbler-support 76F to be rotated beyond a small initial angular distance; because if any one of the six tumblers should not have its gate 86 properly aligned with the barrier-elements of the device 90F, before becoming interlocked therewith, it would subsequently cause a portion of the lower edge-section 267 of such unaligned tumbler to be intercepted; since each of the notches 195F is cut only deep enough to clear the first barrier-element on the flange 187F, but not the next one adjacent thereto, which is disposed closer to the center of rotation of the tumbler-support 76F.

During any attempted picking of the lock, it would of course be necessary, before even a very small rotative movement may be effected in the lock, to first move all of the tumblers at least far enough backwards to release them from the six depressions of the lock-housing (Fig. 63). But after thus releasing the tumbler-support 76F from the detents which hold it in its normal position, it is not possible afterwards to determine by means of a picking tool how far back each of the tumblers must be shifted in order to effect proper alinement between the gate 86 of any tumbler and the barrier-element adjacent thereto, because, as pointed out hereinbefore, the gate 86 on the interceptable edge-section of each tumbler is exactly of the same width as each of the notches 195F arranged on either side thereof.

Fig. 71 clearly reveals that the constructional features of the mechanism are such as to enable the tumblers to be shifted individually to various positions within relatively large limits, thus enabling the tumbler-engaging notches 88F of the key 86F to be cut in at least ten depths; it follows therefore that the number of different keys possible in a lock-mechanism of this type having six tumblers is ten raised to the power of six. Obviously, the number of possible key-changes may be greatly increased by the addition of one or more tumblers. Still further key-changes may be obtained by the provision of lengthwise grooves, as shown on the operating part of the key 86F by the reference character 273, to correspond with similar elements in the key-way of the lock.

As hereinbefore specified, any of the particular lock-constructions of the present invention having barrier-elements disposed at spaced relation with the interceptable parts of the tumblers, may be built in combination with an operatively associated adjunctive device in the form of either a key-hole shutter or a tumbler-interlocking device, or in combination with both the first and second mentioned adjunctive device. A mechanical organization comprising said tumbler-interlocking device and a key-hole shutter is exemplified in the drawing-figures 65 through 67. In Fig. 66 may be seen in cross-section the slightly modified lock-housing 77G, containing a key-hole shutter, which, in the form shown, comprises two interjoined supporting members 274A and 274B to which the tumbler-support 76G is rigidly connected at its front-end. Said tumbler-support is of a construction similar to that illustrated in Fig. 71, but instead of the hub-member 184F the two shutter-supporting members 274A and 274B are adapted to revolvably support the key-operable mechanism at the front-end inside the cylindrical lock-housing 77G. Only a fragmentary view is presented in Fig. 66 of a limited number of those parts which are shown more fully in Figs. 68 through 71. In Fig. 66 may be seen, partly broken away, the cylindrical member 260A; the tumbler 81G, with its gate 86 and the notches 195F; the central tube 257, and the pin 256 inside the key-hole 85F, which extends from the said tube 257 through the shutter-members 274A and 274B, thus merging into the key-hole of the housing 77G; said two shutter-members having a key-hole of exactly the same form as the key-hole of the lock-housing (Fig. 65) so as to enable the key 86G to be inserted into the lock as shown in Fig. 67.

The notched operating end of the key 86G is of a form similar to that shown embodied with the key of Fig. 64, but in rear of said notched end

is formed a wider substantially flat section 275, having a slot 119 into which the inner portions of the two shutters 75F and 75G (Fig. 65) may enter during operation of the device. In Fig. 65, the shutter-supporting member 274B is shown detached from the other shutter-supporting member 274A, so as to clearly reveal the arrangement of the slightly modified key-hole shutters, which are normally held in the operative position as shown in the drawing. A curved spring 115F (Fig. 65) is attached to both key-hole shutters in such a manner that the shutters may be urged by the connected flexible ends of said spring outwardly, apart from each other, thus normally leaving the key-hole of the lock open while the outer end of each shutter projects respectively into a groove or outcut 114F of the lock-housing 77G. On the inner end of each shutter is made a beveled edge to enable these shutter-ends to overlap when the two shutters are moved together during initial rotative movement of the tumbler-support; at which time the outer end of each shutter is forced out of the housing-groove 114F in the same manner as hereinbefore set forth in connection with the device of Fig. 1.

The handle 128F of the key 86G has a serrated edge 129F which serves to indicate by its relative angular position while the key in the lock is rotated over a half turn, whether or not the mechanism is in bolt-locking position.

It will be noted that the two shutters 75F and 75G are made wider than the circular key-hole of the lock. As already stated, the hole in the central tube 257 is of the same diameter as that 35 in the front-wall of the lock-housing, and as alluded to above, the key-way into which the upper and lower edge-section of the flat slotted key-part 275 enters is merely deep enough to accommodate said key-part 275. Hence, this particular 40 key-hole shutter-device possesses the same functional characteristics as the shutter-device shown embodied with the tumbler-mechanism of Fig. 1 and also the modification of Fig. 15. For the attainment of maximum security in a lock embodying a key-hole shutter, of a form as disclosed in this application, there is a feature that deserves particular consideration; said feature relates to the disposition of the barrier-elements, which, in practice, should be arranged so as to be located at 45 a distance sufficiently far away from the interceptable parts of the tumblers to enable the key-hole to be closed by means of the operatively connected shutter before the tumblers are carried very close to or in contact with said barrier-elements. If, therefore, the tumbler-mechanism of 50 the construction shown in Fig. 68 is employed in combination with a key-hole shutter, then the arrangement and the specific form of the tumblers may be suitably altered to permit the barrier-elements on the flange 187F of the barricading device 90F to be disposed much wider apart than 55 shown. This end may easily be accomplished by arranging the tumblers in pairs, as indicated in dotted lines in Fig. 70, where the altered form of two tumblers, bearing reference characters 80F and 82F, is exemplified.

To further elucidate the effectiveness of the shutter-device of the present invention, there is shown in dotted lines in Fig. 66 a picking instrument 276, made of wire, such as might ordinarily be used in an attempt to pick a lock. As fully explained in various sections of this specification, the present invention embodies certain novel features which make it necessary to first rotate the tumbler-support over a relatively small angle

away from its normal position for carrying the tumblers into contact or very close proximity with the barrier-elements of the lock. Accordingly, the device of Fig. 60, when associated with the device of Fig. 66, is adapted during such initial rotative movement of the tumbler-support to effect operation in the key-hole shutters 75F and 75G to close the key-hole of the lock either before or at about the time that the tumbler-interlocking operation is effected, thus making it impossible for any tumbler to be shifted away afterwards from the particular position to which it was moved while still at a distance away from the barrier-elements.

As formerly pointed out in connection with the description of the device of Fig. 1, whenever the shutter of the lock is in a key-hole closing position, only an easily bendable thin wire may conceivably be forced through the narrow tortuous opening left in the key-hole. The undulous channel through which the end of the picking instrument would have to be pushed through to reach the engageable portion of the tumbler 81G is indicated by the inserted section of the picking instrument 276 in Fig. 66; but due to the sharp bends of the wire around the edge of the shutters 75F and 75G, and also due to the bends formed around the wards of the key-hole, it would in practice not be possible to cause the extreme inner end of the wire or picking instrument to be directed toward any portion of any particular tumbler in the lock; and even if it were assumed that contact may be made in some manner between the end of an inserted wire and a tumbler behind the shutter, it would be of no avail because of the obvious impossibility of appreciably altering the position of the tumbler at such time. Thus the present invention embodies means of generically novel character adapted to prevent the effectual use of a picking instrument for the operation of the lock, while permitting its operation in a conventional manner by means of the correct key.

Having now particularly described and ascertained the nature of my invention, I would state in conclusion that, while the illustrated examples constitute practical embodiments of my invention, I do not desire to be restricted to the details of construction and arrangement of parts of the various constructions shown in the accompanying drawings, since manifestly they can be considerably varied without departure from the spirit of the invention.

What I claim as new, and desire to secure by Letters Patent in the United States, is:

1. A lock-mechanism, comprising a revolvable tumbler-support, a plurality of tumblers carried on the support, said tumblers being movable relative to one another to various positions, means to permit the tumbler-support to be rotated over an angle large enough for effecting operation in said lock-mechanism only when said tumblers are disposed in a definite position relative to one another, an adjunctive device arranged to be operated while the tumbler-support is rotated over a limited initial angle of smaller degree than said first mentioned angle; said adjunctive device being adapted to prevent further relative movement to be effected in said tumblers subsequent to rotation of the tumbler-support over said smaller limited angle, a stationary plate permanently fixed adjacent the front-end of the revolvable tumbler-support, the plate having a key-hole with at least one substantially narrow radial extension, and the tumbler-support having a key-way

including a radial groove of substantially identical contour as that of the key-hole in said plate, the groove of the key-way being normally disposed in alignment with said narrow extension of the key-hole to permit insertion of an operating key for shifting the tumblers relative to one another, and an instrumentality co-active with the adjunctive device for causing said radial groove of the tumbler-support to be urged, during said initial angular movement, behind an occluding portion of said stationary plate.

2. In a lock-mechanism, a plurality of key-operable tumblers shiftable relative to one another to enable locking operation to be effected only if the tumblers are first shifted to a definite operative position, a rotatable support adapted for carrying said tumblers, means to permit the rotatable support to be rotated over a limited initial angle irrespective of whether or not the tumblers are disposed in said operative position, an instrumentality arranged to be operated during said initial limited angular movement of the rotatable support; said instrumentality comprising means to prevent the tumblers from being shifted relative to one another subsequent to said limited angular movement of the tumbler-carrying support, a lock-casing embodying a stationary front-plate with a key-hole having two radially extending slots disposed diametrically opposite each other, and the rotatable tumbler-carrying support having a key-way with narrow recesses normally held in alignment with said slots of the key-hole adapted to permit insertion of an operating key, and a device in the lock-mechanism arranged to enable the rotatable tumbler-carrier to be rotated over said initial limited angle to a sufficient degree to cause said narrow recesses of the keyway to be moved behind occluding portions of said stationary plate when operation of said instrumentality becomes effective.

3. A lock-mechanism, comprising a key-operable rotatable tumbler-mechanism, and a housing for its support, detent-means for normally maintaining the tumbler-mechanism in a definite angular position relative to the housing, said detent-means being adapted to positively release the tumbler-mechanism for initial limited rotation with aid of an operating key even if inserted into the lock-mechanism to less than its full extent, and a barricading device adapted to inhibit rotative movement in the tumbler-mechanism beyond a limited angular distance away from said definite angular position unless a preordinated mechanical operation is effected in the tumbler mechanism on or about the time it is disposed in the first mentioned angular position in which it may normally be maintained with co-operation of said detent-means.

4. A lock-mechanism, comprising a plurality of key-operable tumblers adapted to be shifted relative to one another to afford the lock-mechanism to be operated only when the tumblers are shifted to a certain operative position, a rotatable support for carrying said tumblers, a housing including detent-means for maintaining the rotatable support in a definite position to enable proper interaction between an operating key and the tumblers to be effected, barrier-elements arranged at a definite distance away from the intercepting parts of the tumblers before they are shifted relative to one another, means for causing the said barrier-elements and certain intercepting parts of the tumblers to be carried into close proximity with each other during limited 75 initial angular movement of said rotatable sup-

port, an adjunctive device arranged for operation therein to be effected during said limited initial angular movement of the rotatable tumbler-carrying support; said adjunctive device being adapted to prevent the tumblers from being shifted relative to one another on or about the time when the barrier-elements are in close proximity or in contact with one or more tumblers, and a member co-active with said detent-means of the housing, the member being adapted for movement conjointly with at least one of the tumblers to free the tumbler-carrying support for rotation to an extent dependent on the relative position of the tumblers as mentioned.

5. In a lock, a key-operable tumbler-mechanism having a plurality of tumblers adapted to be shifted relative to one another to various positions to enable the lock to be subsequently operated, a revoluble support for the tumblers, a housing for the support, barrier-elements on the housing, the barrier-elements lie in the path of certain interceptable parts of the tumblers but are normally disposed at a definite angular distance away therefrom, and an instrumentality in the tumbler-mechanism for maintaining the tumblers out of contact with said carrier-elements while said shifting operation is effected in the tumblers, said instrumentality comprising a detent-device co-active between the revoluble support and the housing to normally inhibit rotative movement in the support, and members in the detent-device adapted for movement during shifting operation of the tumblers, to free the tumbler-support for rotation over at least a limited initial angle irrespective of the position of the tumblers in relationship with each other.

6. A lock-mechanism, comprising a plurality of tumblers shiftable relative to one another to various positions, a rotatable support for the tumblers, a housing for the support, said housing comprising means for maintaining the rotatable support in a definite angular position relative to the housing before said shifting operation is effected in the tumblers; the lock-mechanism having a key-way adapted for the reception of an operating key while the support is disposed in said definite angular position, a barricading device having spaced-apart barrier-elements arranged to lie in the path of certain interceptable parts of the tumblers but at a definite angular distance away therefrom, means for interlocking the tumblers while they are carried toward said barrier-elements during initial limited rotative movement of said tumbler-support, a shutter-mechanism having a member movable into said key-way during the last mentioned movement of the tumbler-support, a key adapted for shifting the tumblers relative to one another to a particular position to enable subsequent locking operation to be effected, and means on the key to enable the shutter-mechanism to be operated while the key is held in operative position in the key-way of the lock-mechanism.

7. In a key-operable lock, a plurality of tumblers shiftable relative to one another to various positions, means to afford the lock to be operated only after the tumblers have been shifted to a definite position, a revoluble support for the tumblers, an instrumentality to enable the tumblers to be interlocked in more than one particular position within definite limits to either allow or to inhibit subsequent locking operation to be effected depending on the relative position of the tumblers when interlocked; said tumbler-interlocking operation being accomplished during

rotative movement of said tumbler-support over a limited initial angle, a housing for the revoluble support, a stationary plate on the front-end of the housing, said plate having an inside face contiguous with a part of the revoluble support, a detent-device adapted for co-action between the stationary plate and said revoluble support for normally maintaining the latter in a definite angular position in relationship with the housing, and members in the detent-device movable concurrently with at least one tumbler when shifted to free the revoluble support for rotation to the extent permitted by the position of all the tumblers in the lock.

15. 8. In a lock, comprising a cylindrical housing and a tumbler-mechanism rotatably supported therein, a plurality of tumblers arranged for movement relative to one another in a direction lengthwise of the housing, a barricading device 20 having spaced-apart barrier-elements disposed at a definite distance away from the interceptable portions of the tumblers to normally enable them to be freely moved relative to one another without coming in contact with said barrier-elements, 25 each tumbler having at least one gate adapted to be carried during said relative movement of the tumblers into alignment with the spaced-apart barrier-elements to permit the lock to be subsequently operated while the barrier-elements are 30 disposed in said gates, detent-means for normally maintaining said tumbler mechanism relative to the housing in a definite angular position, and a member on at least one tumbler forming part of said detent-means, and movable co-extensively with the last mentioned tumbler to a 35 position to enable the tumbler-mechanism to be subsequently rotated over a limited initial angle in the direction of said spaced-apart barrier-elements, whether or not the tumblers are in position 40 to permit further angular movement of the rotatable support beyond said limited initial angle.

9. A key-operable lock-mechanism, comprising a housing having a key-hole, a rotatable tumbler-support inside the housing; said support having a key-way normally disposed in register with the key-hole of the housing to permit insertion of a key for the operation of the lock-mechanism; a plurality of tumblers carried on said rotatable 45 support, each tumbler having at least one gate arranged in a definite position on a certain interceptable section thereof, a barricading device embodying spaced-apart barrier-elements disposed at a definite distance away from the interceptable 50 sections of the tumblers, the latter being shiftable relative to one another to enable the gate of each tumbler to be carried into alignment with said barrier-elements to avoid their obstruction during subsequent rotation of the tumbler-support, 55 and detent means adapted for maintaining the tumbler-support in a definite position relative to the housing to enable the tumblers to be shifted relative to one another without coming in contact with said barrier-elements during certain definite limits of such shifting operation.

10. In a key-operable tumbler-mechanism, comprising a revoluble support and a housing therefore, a plurality of tumblers arranged on said support, the tumblers being movable to various positions relative to one another, barrier-elements disposed in the path of certain interceptable parts of the tumblers but located at a definite distance therefrom to prevent the tumblers from coming in contact with said barrier-elements 70 while the revoluble support is maintained in a

definite angular position relative to the housing, means on the tumblers adapted to enable them to clear said barrier-elements to permit rotation of the tumbler-support upon movement of the tumblers relative to one another to a definite position, and spring-means arranged on said revolvable support adapted for normally urging the tumblers away from the last mentioned position; said spring-means embodying a plurality of interconnected operating elements forming a unit, each element constituting a flexible extension having its free end held yieldably in pressure contact with a tumbler.

11. In a key-operable lock-mechanism adapted for the operation of an operatively associated bolt-mechanism, a cylindrical housing having a key-hole, a rotatable tumbler-support inside the housing, a plurality of tumblers arranged to be shifted relative to one another within definite limits lengthwise of the cylindrical housing, a stationary barricading device on the housing having spaced-apart barrier-elements arranged at a definite distance away from certain interceptable sections of said tumblers, each tumbler having a gate movable into alignment with said barrier-elements to enable the lock-mechanism to be subsequently operated, and an instrumentality adapted for maintaining the rotatable tumbler-support in at least two different angular positions relative to the housing while the tumblers are held relative to the barrier-elements in a position to enable an operating key to be inserted into said key-hole for shifting the tumblers to the required position to permit the tumbler-support to be subsequently rotated.

12. A key-operable tumbler-mechanism, comprising a housing having a key-hole, a tumbler-support revolvable inside said housing, a plurality of tumblers carried on said support and movable relative to one another to various positions, each tumbler having an interceptable section with at least one outcut thereon, a barrier-device carried on the tumbler-support and movable relative thereto; said barrier-device comprising a member located at a definite distance away from the interceptable sections of the tumblers to permit the latter to be normally shifted on the support without coming in contact with said member, and means co-active between the housing and the barrier-device for effecting movement in the latter during rotative movement of the tumbler-support away from its normal position to enable said member of the barrier-device to be carried into the outcut of the respective tumblers when the latter are shifted to proper operative position; said member being adapted to engage a portion of the interceptable section of any tumbler whose outcut is not in alignment with said member, to thereby prevent rotation in the tumbler-support to be effected beyond a limited initial angle.

13. In a key-operable tumbler-mechanism, a housing having a key-hole, a rotatable tumbler-support inside the housing, a plurality of tumblers arranged on the rotatable support, the tumblers being shiftable relative to one another to various positions, each tumbler comprising an interceptable edge-section having a gate and notches adjacent thereto, each notch being of a width substantially equal to the width of the gate but of lesser depth, a barricading device having spaced-apart barrier-elements disposed in the path of said edge-sections of the tumblers but normally held at a definite distance away therefrom, and an instrumentality between said barrier-elements and the edge-sections of the tum-

blers for effecting interlocking operation in the latter with co-operation of either the gate or the said notches, depending on the particular position in which the tumbler is disposed while carried toward said barrier-elements, the instrumentality comprising means to prevent rotation in the tumbler-support to be effected beyond a limited initial angle if any tumbler has one of its notches in interlocking position.

14. In a lock, a rotatable tumbler-support, a housing therefor, a plurality of tumblers carried on said support, the tumblers being shiftable relative to one another to various positions, each tumbler having an interceptable edge-section comprising a gate and notches thereon to form a row of teeth, a barricading device held on the inside of the housing, barrier-elements on the barricading device arranged to lie in the path of said interceptable edge-sections of the tumblers but normally disposed at a definite distance away therefrom, detent-means on the barricading device arranged between the barrier-elements and the edge-sections of the tumblers for engaging either a notch or the gate of any tumbler when first shifted to a definite position to enable the tumblers to be subsequently interlocked while carried toward the barrier-elements, said notches being cut less deep than the gate of the respective tumblers to cause any tumbler having one of its notches engaged with said detent-means to be intercepted subsequently by said barrier-elements, and an instrumentality interactive between the detent-means and the toothed edge-section of the respective tumblers, adapted to restrict any interlocked tumbler in its slight endwise movement to substantially the same limits whether a notch or a gate of the tumbler is in engagement with said detent-means.

15. In a key-operable lock-mechanism, a rotatable tumbler-support having a key-way, a lock-housing having a key-hole maintained in register with said key-way while the tumbler-support is in a normal position relative to the housing, a plurality of tumblers shiftable within definite limits on said support, means to permit rotation of the tumbler-support to be effected only if the tumblers are shifted to a definite position relative to one another, and a key-hole closing device adapted to be operated when key-actuated rotation of the tumbler-support is effected in a direction away from said normal angular position, the closing device including means to enable an undulous channel to be formed leading from said key-hole of the housing into the key-way of the tumbler-support whenever the latter is rotated in the absence of a key beyond a definite limit of its normal angular position as far as permitted by the disposition of the tumblers, to thereby inhibit the effectual use of a picking instrument for altering the position of the tumblers relative to one another inside the housing whenever the key-hole closing device is operated as mentioned.

16. A key-operable lock, comprising a stationary housing having a key-hole, a rotatable tumbler-support in the housing, said support having a key-way normally maintained in register with the key-hole of the housing, a plurality of tumblers adapted to be shifted to various positions relative to one another, barrier-elements on the housing disposed in the path of certain interceptable portions of the tumblers but normally held at a definite distance away therefrom, means to enable the tumblers to clear the barrier-elements when the tumblers are disposed in a defi-

nite position relative to one another while the support is rotated, a key-hole shutter having a member arranged to move into the key-way of the tumbler-support when the latter is rotated away from its normal position for carrying the tumblers toward said barrier-elements of the housing, an operating key adapted to permit movement of said shutter-member while the operating part of the key is in operative position in the key-way, and an instrumentality operatively associated with key-hole shutter to form a tortuous channel communicating with the key-way of the tumbler-support and the key-hole of the housing when said member of the shutter is urged into said key-way before the operating key is inserted therein, and after rotation of the tumbler-support to a definite degree for urging its key-way out of register with the key-hole of the stationary housing to cause certain portions of the latter to partly obstruct said key-way

17. A key-operable lock, comprising a housing having a wall with a key-hole, a revoluble tumbler-support in the housing, said revoluble support having a key-way normally maintained in register with the key-hole of the housing, means on the housing-wall to enable less than the entire opening of the key-way to be obstructed when the tumbler-support is rotated away from its normal angular position beyond a limited initial angle over that part of an arc within which complete lock-operation may be effected, a tumbler mechanism in connection with the rotatable support adapted to be operated by means of an operating key including a handle projecting to the outside of the housing, and a key-hole shutter having a movable member adapted to obstruct that part of the key-way which is left unobstructed by said means of the housing-wall when the tumbler-support is rotated away from its normal position beyond the limit mentioned.

18. In combination, a key-operable tumbler-mechanism adapted for the operation of an operatively associated bolt-mechanism, a housing for the tumbler-mechanism, said housing having a key-hole to fit a retractable operating key including a projecting handle, a plurality of tumblers in the housing shiftable to various positions relative to one another, means for interlocking said tumblers after having been shifted to a definite position and upon subsequent key-actuated angular movement effected in the tumbler-mechanism, and a key-hole closing device arranged for partially closing said key-hole while the tumbler-mechanism is rotated over an angle within which said bolt-mechanism may be operated.

19. The combination with a key-operable lock-mechanism in a housing having a stationary front-wall with a key-hole, and a key-hole shutter having a spring-actuated member adapted to move first into the key-hole and then out therefrom during a complete cycle of locking operation when accomplished by means of a hand-operated removable key.

20. The combination with a key-operable lock-mechanism in a housing having a non-rotatable front-wall with a key-hole, a key-hole shutter arranged for operation behind said front-wall, a spring-device in connection with the shutter for normally holding the latter away from the key-hole, an operating key including a handle projecting to the outside of the housing when the key is in operative position, means for effecting movement of the shutter relative to said operating key when the key in the lock is rotated, and movable members in the lock-mechanism co-active with a part of the key when inserted to thereby afford subsequent lock-operation to be accomplished.

21. The combination with a lock having a plurality of relatively movable tumblers operatively mounted in a housing comprising a non-rotatable front-plate with a key-hole, a key hole shutter arranged behind said front plate, said shutter being adapted for movement to occlude at least part of the key-hole during the initial operative stage of the lock, and means for interlocking a plurality of tumblers in said housing while movement of said shutter is effected to occlude the greater part of said key-hole in the front-plate of the housing.
